KNITTING MACHINE

Max C. Miller, Cumberland, R. I.

Application June 9, 1938, Serial No. 212,703

78 Claims.

(Cl. 66—82)

The present invention relates to knitting machines, and more particularly to improvements in knitting machines of the general type of which the knitting instrumentalities comprise a series of knitting needles and sinker elements individually movable in accordance with a knitting wave to measure the feeding yarn against the shanks of the needles.

The invention as herein disclosed, is embodied in a multiple section flat knitting machine of the so-called Cotton type, certain features being especially, but by no means exclusively, applicable to the manufacturer of full-fashioned hosiery.

It is a principal object of the present invention to provide in a machine of this general description, novel actuating and controlling mechanisms for the knitting instrumentalities including particularly the yarn measuring sinkers whereby certain objectionable and limiting factors in the operation of such machines are wholly eliminated, the construction of these mechanisms greatly simplified, and a more accurate and dependable operation of the knitting instrumentalities and at higher speeds obtained, together with a greater versatility of adjustment and control during the continuance of the knitting operation.

More specifically, it is an object of the invention to provide novel and improved sinker actuating means well adapted to effect a smooth and an extremely rapid advancing movement of each successively actuated sinker to fully kink the yarn about the shanks of the adjacent needles prior to the start of the advancing movement of the next succeeding sinker, whereby the necessity of employing the usual dividers between alternate sinkers is eliminated, and the speed of the knitting operation at the same time may be greatly increased.

Other objects of the invention are concerned with the provision of novel means for controlling the operation of the individual sinkers to determine loop length whereby a more uniform operation of the machine is secured to produce even appearing fabric loops, and to permit such variations in loop length as may be desired, for example, in the knitting of full-fashioned hosiery.

With these and other objects in view, as may hereinafter appear, a feature of the invention consists in the provision in a knitting machine having individually operable yarn measuring sinkers, of fluid operated means for projecting

the sinkers to kink yarn against the needle shanks.

More specifically, a feature of the invention consists in the provision in a flat knitting machine of sinker actuating means comprising a cylinder extending lengthwise of the sinker series, and having a movable valve member or piston adapted to be traversed first in one direction and then in the other by the conventional Coulier motion or other suitable means, the traverse of the piston causing a fluid medium in the cylinder to impart pressure successively to each of the sinker actuating elements to urge the sinkers forwardly into yarn kinking position.

Another feature of the invention consists in the provision of means for releasing the sinkers successively to cause them to be projected by the aforesaid fluid pressure mechanism in the desired wave-like motion, said mechanism comprising a member which is moved longitudinally of the machine during the Coulier to disengage successively the sinker actuating elements.

Still another feature of the invention consists in providing means for limiting the extent of forward movement of the sinkers upon their release by the sinker holding mechanism, said means comprising a member mounted for movement toward and away from the needle series and serving as an adjustable stop for the entire group of sinkers, whereby the depth of yarn kinking may be varied throughout the length of the needle series to control the tightness or looseness of the fabric.

A further feature of the invention involves the provision in a flat knitting machine, of means for limiting the extent of projection of certain automatically selected sinkers during the yarn kinking movement, whereby reinforced areas may be readily produced by the remaining sinkers and cooperating elements without rocking the needles toward and away from the press edge during the traverse.

Still another feature of the invention consists in the provision of means for automatically positioning the needles during the Coulier in either of two positions only, one position being taken for the production of plain fabric and the other for the production of reinforced fabric.

Other objects and features of the invention will become apparent to those skilled in the art from the following description taken in connection with the accompanying drawings, in which Figure 1 is a view in side elevation, partly in section, of a Cotton type full-fashioned hosiery.

siery knitting machine embodying the invention; Figures 2 to 6 are profile views of certain of the rotating cams for actuating the various knitting instrumentalities, Fig. 2 showing the cam for imparting the press or horizontal in-and-out motion to the needle series, Fig. 3 the cam for the vertical needle movement, Fig. 4 the cam for the catch bar vertical movement, Fig. 5 the lifting cam for the upper sinker rail, and Fig. 6 the cam for the catch bar horizontal movement; Fig. 7 is a view in rear elevation of a portion of the knitting machine, illustrating the Coulier drive for the traversing mechanism; Fig. 8 is a top plan view of the machine, illustrating two sections of the same; Fig. 9 is a view in front elevation of a portion of the machine, showing certain of the actuating mechanism for the needle series of one section, the yarn carrier mechanism, and the pattern chain control means; Fig. 10 is a view in side elevation, taken on the line 10—10 of Fig. 9, illustrating the pattern mechanism for varying the depth of yarn kinking by the sinkers; Fig. 11 is a detail end view of the pattern cam and cooperating levers; Fig. 12 is a side view of the mechanism shown in Fig. 11; Fig. 13 is a plan view on an enlarged scale of one section of the machine, certain parts being omitted to show more clearly the mechanism for projecting the sinkers, and also the verge plate for adjustably limiting the extent of sinker projection; Fig. 14 is a detail view in side elevation of the parts shown in Fig. 13 and taken on the line 14—14 of said figure; Fig. 15 is a plan view on a further enlarged scale of the end portions of adjacent section and illustrating portions of the sinker releasing and positioning mechanisms; Fig. 16 is a sectional view in side elevation taken along the line 16—16 of Fig. 15; Fig. 17 is a detail sectional view of certain of the sinker actuating elements, taken along the line 17—17 of Fig. 16; Figs. 18 to 22 are a series of diagrammatic plan views of the sinker actuating, releasing and positioning mechanism taken on the line 18—18 of Fig. 14 at different times during Coulier or yarn kinking movement of the sinker series; Fig. 18 showing the sinkers in retracted position, with the hydraulic piston and sinker release rail at their extreme left position, just prior to the commencement of the needle movements to form the yarn kinked by the previous traverse into fabric loops; Fig. 19 shows the piston and rail as having commenced their traverse to the right; Fig. 20 is a view of the parts when nearing the end of their traverse to the right, all but a few of the sinkers having been projected; Fig. 21 shows the parts as having traversed still further toward the right, all of the sinkers being in forward position; and Fig. 22 shows the parts at the limit of their traverse to the right and occupying the position corresponding to Fig. 18, but at the right hand end of the section; Fig. 23 is a diagrammatic view of the sinkers, sinker stop bar or verge plate, and supplementing sinker stop rails, showing the parts in the position they assume during the knitting of plain, un-reinforced fabric, the sinkers being stopped in aligned forward position by engagement with the verge plate; Fig. 24 is a view similar to Fig. 23, but with the parts arranged for knitting fabric having reinforced areas, the verge plate being in forward position to permit certain sinkers to be projected beyond those sinkers which are engaged by the supplementary sinker stop rails; Fig. 25 is a view of one form of yarn kinking

sinker having an abutment positioned for cooperation with one of the supplementary sinker stop rails; Fig. 26 is a view of another form of sinker having an abutment positioned for cooperation with the other supplementary sinker stop rail; Fig. 27 is a detail view in front elevation of the sinker release rail, a supporting block therefor, and sinker guard cams; Fig. 28 is a sectional view taken along the line 28—28 of Fig. 10 29; Fig. 29 is an inverted plan view of the parts shown in Fig. 27; Fig. 30 is a detail view of the cam and cooperating lever for imparting the horizontal or in-and-out motion to the needle series, together with the mechanism for positioning the needles, at the time the Coulier is taking place, either in the position for knitting plain fabric or in the position for knitting reinforced fabric, the parts being illustrated at that time in the cycle of the machine when the needles are 15 at the limit of their forward movement, and with the needle positioning mechanism in inactive position; and Fig. 31 is a view similar to Fig. 30, but with the needle positioning means operative to position the needle for the knitting 20 of reinforced fabric.

The invention is herein disclosed in the drawings, as embodied in a multiple section flat full-fashioned knitting machine having for each section, a series of spring bearded needles movable as 30 a unit with relation to a press edge, knockover bits, and cooperating yarn measuring sinkers which are arranged to be advanced in a wave-like motion to sink yarn against the shanks of the needles. The illustrated machine, except 35 as hereinafter more particularly pointed out, follows the usual construction and arrangement of these machines, having a base comprised of cross frames 40 spaced at intervals along the length of the machine, and connected by the usual lower front rail 42, rear rail 44, sinker rail 46, and work table 48, which extends throughout the length of the machine. The machine is driven from a main cam shaft 50 extending along the length of the machine. The spring bearded 40 needles 52 of the machine are mounted on needle bars 54 adapted to move as a unit with relation to a fixed press edge 56 formed on the forward end of the lower sinker bed 58 supported on the sinker rail 46. The supporting 45 and actuating connections for the needles comprise vertically extending hinge pins 58 to which the needle bars are attached, pivotally mounted at 60 on rearwardly extending vertical motion levers 62 secured to a needle vertical motion rock 50 shaft 64 extending along the machine length. Downwardly extending cam levers 66 secured at spaced intervals to the rock shaft 64 carry at 55 their lower ends rollers 68 for engagement with cooperating needle vertical motion knitting cams 60 on the cam shaft 50. Forward and back needle motion is provided through connections which include links 72 connecting the lower ends of the depending lever arms 59 with downwardly extending levers 74 carried on the needle press 65 motion rock shaft 64 extending along the length of the machine. There is also secured to the rock shaft 76, at spaced intervals along the machine length, needle press motion cam levers 78 having mounted thereon cam rollers 79 for engagement with needle forward and back motion cams 80 on the cam shaft 50. The machine is 70 also provided with knockover bits 82 which are constructed and arranged to operate in a manner usual in full-fashioned machines. The machine is also provided with the usual yarn car-

riers 84 supported for traversing movement on carrier bars 86 slidably mounted in fixed brackets 88 (see Figs. 9 and 10).

In accordance with the present invention, applicant provides a novel arrangement of the sinkers, and novel actuating and controlling means for the sinkers and needles cooperating therewith, to measure the feeding yarn against the needle shanks. The novel devices employed, include hydraulically actuated means for actuating the sinkers whereby an extremely rapid and dependable sinkers action is secured, and the usual mechanical operating slur-cock cam and sinker jack construction with its attendant limitations and disadvantages is wholly eliminated. Cooperating with the hydraulic actuating means, applicant provides control means in the form of a guard and release cam which operates to control the advance of the sinkers by the hydraulically actuated means, this cam being constructed and arranged to determine the rate and timed sequence of sinker operation to create the most advantageous form of knitting wave.

Further in accordance with the invention, applicant provides individually movable sinker elements between all the knitting needles of the machine, in place of the usual alternating sinker and divider construction in which the dividers are advanced en masse to re-measure the kinked yarn against all the needles. With applicant's novel sinker actuating and controlling mechanism above described, in which fluid actuating means are employed for projecting the individual sinkers in combination with a release cam for controlling the advancing movement of the sinkers, it has been found possible to insure the full projection of each of successive closely adjacent sinker elements before the next succeeding sinker has advanced to kink the feeding yarn. The knitting wave formed in this manner, may be angled as sharply as may be desired, and is well adapted for the actuation of individually movable sinker elements located between all the knitting needles of the finest gauge machines.

Further in accordance with the invention, applicant discloses automatically adjustable means for controlling the limit of the sinker advancing movement in order to produce necessary adjustments of loop length from course to course in the knitting of full-fashioned hosiery, and also for controlling the limit of advancing movement of selected sinkers in the knitting of individual courses as required, for example, in the knitting of reinforced fabric in which longer loops are to be formed on those needles knitting the reinforced areas.

The novel mechanisms hereinafter described, forming the several features of the invention, are adapted for application to existing cotton type full-fashioned hosiery machines, with only such changes and modifications in the operation of the cooperating mechanisms, as herein-after more fully set forth.

In accordance with the present invention, applicant provides two distinct forms of sinker element 90 and 92 illustrated in Figs. 26 and 25 respectively. Sinker elements 92 are employed in the left hand half of each needle series, and sinker elements 90 are employed in the right hand half of each knitting section. As particularly indicated, for example, in Fig. 24 of the drawings, sinker elements 90 differ from sinker elements 92 only in the location of certain of the operating butts, as hereinafter more fully described.

The sinkers are slidably supported in grooves formed in a bottom sinker bed 94 and in a top or cover sinker bed 96, these two beds being bolted to each other and to the sinker rail 46.

- 5 As best shown in Figs. 25 and 26, each of the sinkers 90 and 92 is provided with a cutaway portion 98 to receive the adjustable verge plate hereinafter described, and at the rear end thereof with an abutment 100 against which the verge plate operates. Each sinker is also provided at its rear end with a downwardly extending butt 102 for engagement with the notched bar which in the illustrated construction, and as more fully to be described, is located beneath the sinkers. Each of the sinkers 90 is also provided with two recessed portions having rear end abutments 104 and 106 for sliding engagement with subsidiary verge plates, and each of the sinkers 92 is similarly provided with recessed portions having rear end abutments 108 and 110, the butt 102 being spaced slightly to the rear of butt 104, and butt 110 being spaced slightly in advance of the butt 106 on the sinker 90 for selective engagement with subsidiary verge plates hereinafter more fully to be described. As best shown in Figs. 16, 25 and 26, all of the butting surfaces of the sinkers 90 and 92 are located within the planes of the top and bottom guide surfaces designated respectively at 109 and 111 of the sinkers 90 and 92 which engage within the slotted portions respectively of the cover sinker bed 96 and the bottom sinker bed 94, so that the sinkers may be readily withdrawn forwardly through the slotted guide support provided by the beds 94, 96, in the event that it becomes necessary to replace any sinker or sinkers.

Cooperating with each of the sinkers 90 and 92, is a slider 112 (see Figs. 16 and 17), these 40 sliders being guided in grooves formed in a supporting bar 114 secured to the cover of sinker bed 96, and being further supported toward their rear ends in a bar 116 rigidly supported on a fixed portion of the machine. Each of the sliders 112 is provided with an abutment 118 which engages with the rear end of the cooperating sinker and a forwardly extending groove portion 120 to receive the rearwardly extending upper edge of the sinker. Each of the sliders 50 112 is also provided with an upwardly extending butt 122 for engagement with the sinker guard and release cam hereinafter more fully to be described. Each of the sliders 112 is also provided with a rearwardly extending butt for engagement with the fluid actuated advancing pins hereinafter described. As best shown in Figs. 16 and 17 of the drawings, these butts for the several sliders are staggered with relation to one another, every third slider having a butt 124, and the intervening sliders having butts 126 and 128 respectively.

Applicant's novel fluid actuated mechanism for successively projecting the sinkers, is supported in the machine directly to the rear of the sinkers and sliders above described, substantially in the position normally occupied in these machines by the sinker jacks, slur-cock cams and associated mechanisms. The fluid actuating sinker projecting mechanism is supported on a fixed supporting bar 130 which extends throughout the length of the machine, and is drilled to receive sinker operating pins 132 in staggered relation to one another for engagement respectively with butts 124, 126 and 128 of the sliders 70 112. These actuating pins 132 are in turn acted

upon by a second series of pins 134 supported directly to the rear of and in axial alignment with the pins 132. The pins 132 are slidably supported to slide in holes drilled in a fixed support 136, one such support being provided for each knitting section extending along the length thereof, and bolted to the supporting bar 138. The pins 134 at their rear ends are arranged to be acted upon by the fluid medium contained in a sinker projection cylinder 138 which extends along the length of the knitting section, and is in turn secured to the support 136. In order to positively limit the movement of the actuating pins 134 in each direction, each pin is provided at its forward end with an enlarged head 140 which engages within a correspondingly enlarged portion 142 of the bores within which the pins are fitted to slide. With this construction it will readily be seen that rearward movement of the pins 134 is limited by engagement of the heads 140 with the shouldered rear ends of the enlarged bores 142, forward movement being similarly limited by engagement of the heads 140 with the adjacent face of the supporting bar 138. As best shown in Fig. 16 of the drawings, this face portion of the bar 138 is cut away to provide an exhaust outlet 144 to take care of any leakage of fluid medium past the actuating pins 134. The outlet 144 extends along the entire length of the machine, and is connected to an exhaust conduit 146 through which fluid collected in the outlet 144 is returned to the sump (not shown).

With the preferred construction illustrated, actuation of the pins 134 is effected by a fluid medium, preferably oil, which is admitted under pressure to the cylinder 138. As best shown in Figs. 13, 14, 16, and 18 to 22 inclusive, one such cylinder 138 is provided for each knitting section extending along the length thereof. The several cylinders 138 are provided at each end with outwardly extending flanges 148 which are bolted together to provide a continuous assembly of the cylinder units along the entire length of the machine. There is provided for each cylinder 138, a piston 150 supported on a piston rod 152 which extends the length of the cylinder 138, and abuts at each end against the piston rods 152 of the adjoining cylinders 138 associated with the adjacent knitting sections of the machine. The piston rods 152 are slidably supported at each end of the cylinders 138 in bushings 154 secured to the inner faces of the flanges 148. Each of the piston rods 152 is provided at opposite ends with a small projecting spring-presser ball detent and a recess which fit into correspondingly formed end portions of the next adjacent piston rods 152, and are rigidly held together to move as a unit by means of cross heads 160 and 161 secured to the projecting ends of piston rods at opposite ends of the machine, and connecting rods 162 and 164 which are spaced respectively above and below the cylinders 138, and rigidly connect together the cross heads 160 and 161. The cross head 160 at the right hand end of the machine, is shown in Fig. 8 of the drawings, and the cross head 161 at the left hand end of the machine being shown in Fig. 10. With the construction above illustrated, it will readily be seen that any individual cylinder 138 with its associated piston 150 and piston rod 152, may be readily removed without disturbing the remaining portions of the assembly along the length of the machine, it being necessary only to move the piston rods 152

to their extreme position to the right, as shown in Fig. 22, in which the abutting portions of the piston rods 152 are aligned with the flanges 148.

Each cylinder 138 is formed at each end thereof, with a flange-like base 166 (see Figs. 13 and 14) to which is rigidly secured a valve unit comprising a valve housing 168, chambered for an exhaust valve 170 and a pressure valve 172 through which fluid pressure may be exhausted or admitted to opposite sides of the respective pistons 150. The exhaust valve 170 comprises the exhaust chamber 171 and a valve plunger 174 which is journalled to slide in a rearwardly extending bore in the casing 168, and is spring-seated by means of a small compression spring 176 coiled about the plunger 174 between an abutting portion of the casing 168 and a head 178 formed on the rear end thereof. The pressure valve 172 similarly comprises the chamber 173 and a valve plunger 180 which is spring-seated by means of a compression spring 182 interposed between an abutting portion of the casing 168 and a plunger head 184 formed on the rear end thereof. Each of the chambers 171 of the several exhaust valves is connected through a branch conduit 186 with an exhaust conduit 188 extending along the length of the machine, through which exhausting fluid is returned to the machine sump. Similarly, each of the chambers 173 of the several pressure valves spaced along the length of the machine, is connected by a branch conduit 190 to a main pressure pipe line 192 which extends along the length of the machine, and is connected to the fluid pressure source of supply. It will be understood that fluid pressure may be supplied to the machine through a fluid pressure system which may be of ordinary description, comprising a reservoir located in the machine base, fluid being drawn from the reservoir under pressure by an oil pump, and thereafter returned through the exhaust lines above described, to this reservoir or sump. Inasmuch as fluid pressure systems of this general description are well known, it is believed unnecessary to specifically illustrate the same.

As hereinafter more fully set forth in connection with the description of the operation of the machine, the pressure and exhaust valves 172 and 170 are arranged and operated in such a manner as to cause fluid pressure to be admitted to the trailing side of each of the pistons 150 during their traverse in each direction, and to be exhausted from the leading side of these pistons, so that fluid under pressure is supplied successively to the actuating pins 134 to effect successive projection of the sinkers during the travel of the pistons in each direction. For example, during the travel of the pistons 150 to the right, the pressure valve 172 at the left hand end of each knitting section will be open and the exhaust valve 170 closed, while the corresponding pressure valve 172 at the right end of each section is closed, and the exhaust valve 170 is opened. When the direction of traverse of the pistons 150 is reversed, the positions of all the pressure and exhaust valves will also be reversed.

The mechanism through which the operation of the pressure valves 172 and exhaust valves 170 is controlled, comprises for each valve unit, a cam actuated rocker lever 200 which is supported to turn on a fixed pivot 202, and is provided with rocker arms 204 and 206 which are arranged for alternative engagement respectively with the heads 178 and 184 of the exhaust and pressure

valves. A tension spring 208 secured at one end to rocker arm 204, and at its other end to a hook on the casing 168, tends normally to maintain the cam rocker lever 200 in exhaust position. The operation of the cam rocker levers 200 is controlled through connections which comprise a cam shaft 210 extending along the length of the machine, having mounted thereon operating cams 212 and 214, one such cam 212 being arranged to act upon roller 216 carried by cam rocker lever 200 associated with the valve unit 168 at the left hand end of each knitting section, and one such cam 214 being provided to act upon roller 218 and cam rocker lever 200 associated with each right hand valve unit 168 for the several knitting sections. It will be noted particularly from Figs. 13 and 14 of the drawings, that the cams 212 and 214 are identical in shape, each having four equally spaced rise and intervening low portions, the cams 214 being set at a 45° angle from one another, so that the valve units at opposite ends of the several sections will always be set in reverse positions.

The cam shaft 210 is rocked to effect the desired setting of the valves 170 and 172, and pistons 150 are traversed during each knitting cycle of the machine through a Coulier driving mechanism which is in addition to the usual Coulier drive for the machine. As best shown in Fig. 7, this mechanism comprises a Coulier arm 220 supported at its lower end on a stationary pivot 222 and at its upper end connected by means of a shoe 224 to a piston traversing slide 226. A driving link 228 connected at one end to the Coulier arm 220 and at its other end to a supporting lever (not shown) carries cam rollers 232 spaced to engage opposite sides of a Coulier cam 234 which is continuously driven from the main cam shaft 50 of the machine. These connections include a rearwardly extending shaft 236 to which the Coulier cam 234 is secured, a bevel gear 238 on the shaft 236, and a driving bevel gear (not shown) on the cam shaft 50.

The piston traversing slide 226 is sleeved for traversing movement on a fixed shaft 242, and also upon an additional supporting shaft 244 extending lengthwise of the machine. The slide 226 is formed with a forwardly extending arm 246 which is forked at its forward end, the forks being rigidly secured to the piston connecting rods 162 and 164 (see Fig. 1).

The cam shaft 210 is rotated through a 45° angle at each end of the Coulier stroke, through connections (see Figs. 1, 7 and 8) which include a ratchet 248 secured to the cam shaft 210, and a pawl 250 supported on an axially movable spring retracted plunger 252. The plunger 252 is mounted to slide in an arm 254 rigidly secured to a fixed shaft 256 extending lengthwise of the machine. The pawl 250 is tensioned in a direction to maintain the engagement of the pawl with the ratchet by a small tension spring 257 connected at one end to a rearwardly extending tail of the pawl 250, and at its other end to the fixed lever arm or bracket 254. The rear end of the plunger 252 projects rearwardly beyond its support 254, and is arranged to be engaged by a cam 260 formed on the piston traversing slide 226. As shown in Fig. 8, the traversing slide 226 is at the extreme left hand end of its traversing movement, so that the rise portion of the cam 260 is engaged against the rear end of the plunger 252 to advance the ratchet 248 and cam shaft 210. In order that the cam shaft 210 may be racked to reverse the valve settings at the right

hand end of the Coulier movement, a second racking mechanism for the cam shaft 210 is provided for actuation by the cam 260 at the right hand end of its traverse. As shown in the rear elevation of Fig. 7, this mechanism is identical in construction and mode of operation with the racking mechanism previously described including a ratchet 264 and associated pawl, and plunger 266 supported in a rearwardly extending arm 268 supported on the stationary shaft 266. This racking mechanism is spaced from the racking mechanism illustrated in Fig. 8, the length of the traversing stroke of the piston traversing slide 226.

The present machine is also provided with the usual Coulier motion which in the illustrated construction is employed to traverse the friction driving rod for reciprocating the yarn carrier bars 86 in the usual manner, and also to traverse the sinker guard and release cam mechanism hereinafter to be described. As best shown in Figs. 1 and 7, the Coulier drive comprises a Coulier arm 270 supported at its lower end on a fixed pivot 272, and at its upper end connected to a driving shoe 274 to drive the usual Coulier slide 276. A Coulier driving link 278 connected at one end to the Coulier arm 270, and at its other end to a supporting lever arm 280, carries cam rollers 282 and 284 arranged to engage opposite sides of a Coulier cam 286. The driving connections for the Coulier cam 286 includes a rearwardly extending shaft 288 on which the cam 286 is carried, and intermeshing bevel gears 290 and 292 mounted respectively on the shaft 288 and on the main cam shaft 50 of the machine.

In order to control the advancing movement of the sinkers projected by the fluid pressure actuated mechanism above described, applicant provides a guard and release cam mechanism which operates to prevent the premature advance of individual sinkers, and thereafter to control the projection of the sinkers in such a manner as to produce a uniform steeply angled knitting wave which will insure a rapid but controlled advance of each successive sinker prior to the engagement of the next succeeding sinker to kink the feeding yarn during traverse in each direction. The sinker guard and release cam mechanism, as best shown in Figs. 1, 15, 16, and 27 to 29 inclusive, comprises a sinker traversing rail 294 extending throughout the length of the machine, which is slidably supported in blocks 296 spaced at intervals along the machine length between adjoining sections. The blocks 296 are rigidly secured to and are supported on frame levers 298 (see Figs. 8, 15 and 16) pivotally supported at their rear ends on the fixed shaft 256 between collars 300. The assembly including the cam rail 294 and frame levers 298 is moved vertically through connections which comprise links 302 supported at their upper ends to certain of the frame levers 298, and at their lower ends to co-operating cam levers 304 pivoted on a shaft 306, and provided with rollers 308 for engagement with lift motion cams 310 on the cam shaft 50 of the machine. One such cam is shown in detail in Fig. 5 of the drawings. Lengthwise sliding movement is imparted to the sinker guard cam rail 294 from the Coulier slide 276, which has formed thereon a forwardly extending arm 312 rigidly connected to the guard cam rail 294 (see Fig. 8).

As best shown in Figs. 16, 18 to 22 inclusive, and 27 to 29 inclusive, there is secured to the under side of the sinker guard cam rail 294, a se-

ries of guard cams 314, one such guard cam being provided for each knitting section, and extending slightly beyond the length of the needle series in each direction for engagement with the guard cam butts 122 of the sinker sliders 112. There is also provided at the right hand end of each guard cam, a downwardly extending arcuate-shaped release cam 316 which is slidably supported in an arcuate guideway 318 in the under side of the guard cam rail 284 for movement into and out of operating position with relation to the slide or butts 122. There is similarly provided at the left hand end of each guard cam 314, an arcuate-shaped depending release cam 320 which is slidably supported in an arcuate guideway 322 formed on the under side of the rail 284 for movement into and out of operating position with relation to the slide or butts 122. A spring-pressed detent 324 supported on the rail 284, is arranged for engagement with either of two notches 326 or 328 formed in a slide support 329 for the release cam 316 to support the release cam 316 in either of its alternative extended or retracted positions. A spring-pressed detent 330 is arranged for alternative engagement with notches 332 or 334 in the slide support 336 for the release cam 320 to support said cam in its alternative retracted and extended positions.

During each knitting cycle of the machine, the rail 284 is traversed by the usual Coulier motion above described, through a distance which is somewhat in excess of the needle series first in one direction and then in the other, so that each guard cam 314 will move from its initial position in front of one knitting section to a substantially identical position opposite the next knitting section. During the traversing movement of the rail 284 to the left, the right hand or trailing release cam 316 will occupy the advance position illustrated in Figs. 18 and 29, the left hand release cam 320 associated with each guard cam 314 being in its retracted position. During this traversing movement the sinkers successively projected by the fluid pressure mechanism above described, will be first restrained by the engagement of the slider butts 122 with the guard cam 314, and will then be successively released as these butts come in contact with the sloping surface of the release cam 316. The advancing end of each guard cam 314 which now moves into position opposite the next adjacent knitting section to the left, will pass behind the slider butts 122. During the subsequent rotation of the main cam shaft to complete the knitting cycle, the sinker guard cam rail 284 is raised by the operation of the lift motion cams 310 to permit the retraction of the sinkers and the sliders 112, when the sinker rail 284 is again lowered into the operating position shown, for example, in Figs. 16 and 18, preparatory for the next traversing movement to the right. At the beginning of this traversing movement to the right, the relative positions of the release cams 316 and 320 associated with each section, is reversed, the release cam 316 now being retracted, and the release cam 320 which now becomes the trailing or operative cam, being advanced.

In order to effect this relative positioning movement of the release cams 316 and 320, there is secured to each block 286, a spring-seated actuating element in the form of a leaf spring 340 bolted to the supporting frame lever 288, and provided at opposite ends thereof with trip members 342 and 344 which are arranged for cooperative engagement with actuating pins 346

and 348 formed on the upper surface of the slide support 329, and pins 350 and 352 formed in the upper surface of the slide support 336 for the release cam 320. As best shown in the bottom plan view Fig. 29, the trip members 342 and 344 are so located as to be in the path of movement of the rearwardly disposed one of the two pins associated with each of the release cams 316 and 320. The inner faces of each of the trip members 342 and 344 are vertically disposed for operative engagement with the pins, the outer surfaces being cammed outwardly to permit the pins when engaged against these cammed outer surfaces, to ride beneath the trip member without shifting the position of the associated relief cam. Assuming the position of the parts shown, for example, in Figs. 18 and 27, the movement of the sinker guard cam rail 284 to the right, will now cause the latch member 342 to engage with the rearwardly disposed pin 350 to shift the left hand or trailing relief cam 320 to its operative position, the position of the parts being then as shown in Fig. 19. Continued traversing movement of the rail 284 to the right, subsequently causes the trip member 342 to engage with the rearwardly disposed pin 346 to shift the right hand or leading relief cam 316 associated with each guard cam 314 to its retracted position, this retracting movement being arranged to take place before the leading relief cam 316 reaches the first operating sinker of the knitting section. The positions of the relief cams 320 and 316 will then be as shown in Fig. 20. During the subsequent traversing stroke to the left, the positions of the relief cams 316 and 320 will be reversed through the operation of the trip member 344.

In the illustrated construction, a novel arrangement of the usual catch bar motion is employed for controlling the operation of the sinkers subsequent to the yarn measuring operation to impart the usual forward and back selvage forming and subsequent retracting movements to the sinkers. As best shown in Figs. 1 and 16 of the drawings, a catch bar 360 is provided located rearwardly of the sinker bed 94 and beneath the sinker line. The catch bar 360 is provided with a slot 362 to receive the sinker operating butts 102, the front lip of the slot 362 being shorter than the rear lip to permit relative movement of the catch bar 360, so that the sinker butts 102 may be moved relatively over the front lip into engagement with the rear lip to accurately engage the butts within the slot. The catch bar 360 is supported at intervals along its length on rearwardly extending supporting lever arms 364. The catch bar levers 364 are supported for forward and back movements on upwardly extending lever arms 366 secured to a rock shaft 368 extending along the machine length. Rocking motion is imparted to the shaft 368 by means of one or more cam levers 370 secured to the rock shaft 368, and provided at their lower ends with rollers 372 for engagement with forward and back catch bar motion cams 374 on the cam shaft 50, one such cam being specifically illustrated in Fig. 6 of the drawings. Vertical movements are imparted to the catch bar 360 through connections which comprise links 376 connected at their upper end to the respective catch bar levers 364, and at their lower ends to rearwardly extending arms of cooperating cam levers 378 supported on the supporting shaft 306 extending along the length of the machine. Each of the cam levers 378 is provided with a roller 380 for engagement with cooperating catch bar vertical motion cams

382 on the cam shaft 50, one such catch bar vertical motion cam being specifically illustrated in Fig. 4 of the drawings. In order that the catch bar 360 may be maintained in operating position with the rollers 380 in engagement with their cams 382, each catch bar lever 364 is provided with a rearwardly extending tail to which is secured the tension spring 384.

In accordance with certain features of the present invention, applicant provides novel means for controlling the limit of the advancing movement of the sinkers which is automatically adjustable to vary the length of the sunk loops. During normal knitting, the advance of the sinkers is arrested by the engagement of the sinker abutment 100 with an adjustable verge plate 390 which is arranged normally to engage with the abutments 100 of all the sinkers to limit the advancing movement of the same. The verge plate 390 extends throughout the length of the machine, being supported at intervals along its length upon rollers such as that designated at 392 in Fig. 16, and upon supporting pins 394 which are fitted into slots 396 in the verge plate, and are screw-threaded into the sinker bed 94 to permit a shifting of the verge plate lengthwise of the machine. The lengthwise movement of the verge plate 390 operates to produce a forward or back adjustment of its operating position to adjustably determine the forward limit of the advancing movement of the sinkers and the length of loop measured thereby. To this end the verge plate is provided between the ends of adjacent sections on the forward side thereof, with a wedge cam-shaped bearing surface 400 which is arranged to engage against a correspondingly cammed stationary support 402 fixed to the sinker bed 94. Compression springs 404 coiled about each of the supporting pins 394 between the enlarged head thereof and the rear face of the verge plate 390, serve to maintain the verge plate in operating position with the surfaces 400 in engagement with their correspondingly cammed supports 402.

Further in accordance with the present invention, applicant provides pattern mechanism for automatically controlling the position of the verge plate 390 to effect desired adjustments of loop length during continued operation of the machine. As best shown in Figs. 9 to 12 inclusive, this pattern mechanism comprises a multiple face cam disk 406 sleeved to turn on a fixed shaft 408, a collar 410 secured to the shaft being provided to prevent endwise movement of the cam 406. Cooperating with the cam disk 406 is a downwardly extending lever 412 which is supported to turn on a pivot pin 414, and is provided with an upward extension 416 which engages against the left hand end of the verge plate 390, as shown in Fig. 9. A tension spring 418 connected at one end to the verge plate 390 and at its other end to a fixed point on the machine, acts to maintain the verge plate 390 at all times in engagement with the lever 416. The cam actuated lever 412 is forked at its lower end to provide support for a transversely extending pivot shaft 420 on which are supported four manually adjustable cam follower levers 422 which are arranged for engagement respectively with each of the four face cams 423 on the cam disk 406. The position of each of the cam followers 422 on the cam lever 412 is determined by means of two cooperating set screws 424 and 426. The set screw 424 is screw-threaded into a depending bracket 428 formed integrally with the cam lever 412 for

engagement against the rear side of the corresponding arm 422. The set screw 426 is screw-threaded into a rearwardly extending tail of each arm 422 for engagement against the bracket 428.

5 With this construction it will readily be seen that the adjustment of the verge plate is determined for any particular angular position of the cam disk 406 by the engagement of a selected cam follower arm 422 with a high portion of its co-operating face cam 423.

Mechanism is provided which is controlled from the main pattern chain of the machine for imparting step-by-step rotational positioning movements to the cam disk 406, in order to bring any 15 selected lever arm 422 in engagement with the high portion of its cooperating cam 423. This mechanism comprises a ratchet 430 fixed to the sleeve hub of the cam disk 406, and a cooperating pawl 432 which is pivotally supported on an 20 upwardly extending pawl actuating lever 434. A small tension spring 436 connected between the tail of the pawl 432 and the lever 434 acts to maintain the pawl in engagement with the ratchet. As best shown in Fig. 10 of the drawings, the pawl actuating lever 434 is mounted to turn on a fixed pivot 438, and carries on a 25 forwardly extending arm thereof, a laterally shiftable roller 440 which is adapted for engagement with an actuating cam 442 on the cam shaft 50.

The roller 440 is shifted into and out of operative engagement with its operating cam 442 to start and stop the indexing movement of the face cam 406 through connections controlled from 30 the main pattern chain of the machine, diagrammatically shown at 444. These connections include a shifting fork 446 supported on a slide rod 448 and connected to the sleeve hub of the cam roller 440. The slide rod 448 is connected 35 by means of a link 450 to a pattern chain lever 452 which is adapted to be engaged by a bump such as that indicated at 454 on the pattern chain 444 to shift the roller 440 into operating 40 engagement with its cam 442.

45 In the preferred construction illustrated, novel means are provided for positioning the needles during the Coulier to cooperate with the yarn measuring sinkers which are controlled as above set forth, through the adjustment of the verge plate 390 to vary loop length as required during 50 the course of the knitting operation. In the preferred construction illustrated in the drawings, the usual stitch adjustment for controlling loop length has been eliminated. The usual loop regulator shaft extending along the length of 55 the machine, has been retained, and in the present construction forms part of a mechanism for automatically positioning the needles in a fixed position for cooperation with the sinkers during the yarn measuring operation. With the construction illustrated, the needle positioning mechanism referred to, is constructed and arranged for positioning the needles alternatively in either 60 of two such positions, one being employed during the knitting of courses in which the same length of needle loop is to be measured across the entire course, the other position being employed during the knitting of reinforced fabric to cooperate with applicant's supplementary verge plate mechanism hereinafter more fully to be described, for positioning the needles during the knitting of reinforced fabric in which different lengths of loop are to be measured on selected portions 65 of each needle series. As best shown in Figs. 9, 10, 30 and 31, the machine is provided with a

rock shaft 460 which comprises the usual regulator shaft extending along the length of these machines. Rigidly secured to the rock shaft 460 are a number of upwardly extending detent levers 462, one such lever being provided to cooperate with each in-and-out cam motion lever 78 which has rigidly secured to the hub thereof, a forwardly extending lever arm 464 which carries two adjustable stop screws 466 and 468 adapted for engagement respectively with cooperating stop surfaces formed on the two prongs 470 and 472 of the forked upper end of the detent lever 462. As shown in Fig. 10 of the drawings, the prong 472 is spaced rearwardly of the prong 470. During normal operation of the machine, to knit fabric loops having the same length across the entire course, detent lever 462 is positioned prior to the movement of the needles to their Coulier position, so that the stop screw 468 will be brought into operative engagement with the stop surface provided by the prong 470. During subsequent movement of the needles outwardly and down to the knockover position, the shaft 460 is rocked to move the stop lever 462 rearwardly to permit unobstructed operation of the needle in-and-out motion cam lever 78, this position being shown in Fig. 30 of the drawings. For rocking the lever 460, a rearwardly extending cam lever 474 is secured to the shaft 460, and carries at its rear end a roller 476 arranged to be acted upon by a cam 480 on the main cam shaft 58 of the machine. The forward position of the rock shaft 460 and stop lever 462 is controlled by means of a latch 482 supported on a fixed pivot 484 on the machine frame, which engages with an abutment 486 rigidly secured to turn with the rock shaft 460. A tension spring 488 connected to a forwardly extending abutment 490 rigidly connected to the rock shaft 460, tends to rock the shaft 460 outwardly when permitted by movement of the roller 476 opposite a low portion of its cam 480, to the limiting position determined by the latch 482.

In accordance with certain features of the present invention, applicant provides a subsidiary sinker verge plate mechanism for varying the extent of advance of selected sinkers along the needle series, this mechanism being intended for use in the knitting of fabric courses in which long loops are required in certain portions only of each course as, for example, in the knitting of reinforced hosiery, when it is desirable to employ longer loops in the knitting of the reinforced portions. This mechanism comprises two subsidiary verge plate carrier rails 492 and 494 extending along the length of the machine and slidably supported, as best shown in Fig. 16, in grooves 496 and 498 formed in the cover sinker rail 96. The auxiliary verge plate carrier rail 492 is provided on its under side with an auxiliary verge plate 500 which projects downwardly into the path of movement of the sinker butts 104 of the sinkers 98 comprising the right hand half of the sinker series. As best shown from the construction lines on Figs. 25 and 26, the auxiliary verge plate 500 does not engage with the abutments 108 of sinkers 92 which are placed rearwardly a sufficient distance to prevent such engagement. Similarly, the sinker verge plate rail 494 is provided at each section with a downwardly projecting auxiliary verge plate 502 which projects into the path of movement of the butts 110 of sinkers 92 forming the left half of each sinker series. From Figs. 25 and 26, it will readily be seen that the auxiliary verge plate 502 does

not contact with the abutments 108 of the right hand sinkers 98, these abutments being placed rearwardly with relation to the butts 110 to prevent such engagement. The auxiliary sinker verge plate rails 492 and 494 are spring-seated downwardly by compression springs 504 to position the auxiliary verge plates 500 and 502 against the slotted portions of the sinkers. For convenience of illustration, the auxiliary verge plates 500 and 502 have been designated in solid black lines to show the position of these plates with relation to the sinker series.

With this construction and arrangement of the auxiliary verge plates and the cooperating sinker butts, it will readily be seen that the number of sinkers which will be controlled by this auxiliary mechanism, may be readily determined by adjusting the relative positions of auxiliary verge plate rails 492 and 494 as, for example, when the rail 492 is moved to the left, the number of sinkers in the right half of the sinker series which will have their butts 104 engaged against the verge plate 500, will be diminished. As previously pointed out, the sinkers in the left half of the sinker series are not controlled by the verge plate 500, the abutment 108 being, as previously stated, set back. Similarly, movement of the auxiliary verge plate rail 494 to the right from the position shown in Figs. 23 and 24, will reduce the number of sinkers 92 forming the left half of the sinker series which will be controlled by the verge plate 502 through the engagement of the verge plate with the sinker butts 110. As previously pointed out, the verge plate 502 does not affect the operation of sinkers 98 of which abutments 108 are set back.

During normal operation of the machine, for the knitting of plain fabric, the advance of all the sinkers is controlled, as previously described, by the adjustable verge plate 390 which is so positioned as to arrest the sinker advance through the engagement of the verge plate with sinker abutments 108 before the butts 108 and 110 can contact with the respective auxiliary verge plates 500 and 502. In order to render the auxiliary verge plate mechanism above described, operative to produce a selected control of loop length in the knitting of each course, it is proposed to move the verge plate 390 to an abnormally advanced position and at the same time to move the needles to an abnormally advanced Coulier position toward the front of the machine, so that the auxiliary verge plates 500 and 502 may be rendered operative to control the projection of the sinkers forming the middle portion of each needle series. The positions of the needles and of the verge plate 390 in this position are so gauged as to cause relatively longer loops suitable for the knitting of reinforced fabric, to be formed by the sinkers which are permitted to advance until stopped by the engagement of their abutments 108 with the verge plate 390. In this abnormal forward position of the parts, the auxiliary verge plates 500 and 502 will operate to permit a relatively shorter advance of the sinkers controlled thereby, to form relatively small or normal size loops.

The movement of the verge plate 390 to the abnormal advanced position is effected through the operation of the pattern mechanism above described, when the cam disk 406 is racked to a position in which the follower arm 422 associated with the outside face cam 423 is brought into engagement with the high bump 510 as shown in Fig. 12, which operates through the

connections above described, to shift the verge plate 390 to an extreme position to the right. This movement of the verge plate also operates to shift the knitting needles to an abnormally advanced Coulier position by disconnecting the latch 482 from its abutment 486 on the rock shaft 480, so that the detent levers 482 are permitted to move to the extreme forward position shown in Fig. 31, determined by the engagement of follower roller 476 with the low portion of its cam 480. For this position of the latch levers 482, the extent of the forward rocking movement of the needles is controlled by the engagement of the stop pin 488 with the stop surface formed on the prong 472 of the lever 482. The connections through which the latch 482 is moved out of operating position, comprise an actuating lever 512 (see Fig. 9) supported on a rock shaft 514, and arranged at its upper end to be engaged by an abutment 516 on the verge plate 390 when the verge plate is moved to its extreme position to the right. The rocking movement thus imparted to the actuating lever 512 acts through a downwardly extending lever arm 513, a connecting link 518, a bell-crank 520 and a downwardly extending link 522 connected at its lower end to a rearward extension 524 of the latch lever 482 to disengage the latch. A small tension spring 526 connected at one end to the rearward extension 524, and at its other end to a fixed arm 528, tends normally to maintain the latch 482 in its engaging position shown, for example, in Fig. 10.

With the construction above described, it will readily be seen that the auxiliary verge plate mechanism may be thrown into and out of operation for the knitting of reinforced fabric, by means of the operation of a single control on the main pattern chain which operates through the connections above described, to index the face cam 406 to the proper position. The auxiliary verge plate mechanism will then remain in active operation until further indexing movement is imparted to the face cam 406 to move the high bump 510 out of engagement with its cooperating follower arm 422 to permit the return of the verge plate 390 to a normal operating position to the left. This movement of the verge plate to the left, simultaneously acts through the connections above described, to permit the return 50 of the latch 482 under the influence of its spring 526 to normal operating position as shown in Fig. 10.

Further in accordance with the present invention, mechanism is provided for automatically adjusting the relative positions of the auxiliary verge plate rails 492 and 494, to cause the adjustment of the verge plates 500 and 502 to correspond at all times with the width of plain and reinforced fabric areas being knitted on the needle series. If it be assumed, for example, that a French high splice is being knitted, as the high splice area formed by the reinforcing knitting yarns is widened inwardly, a corresponding adjustment in the position of the auxiliary verge plates 500 and 502 must be effected to cause the added needles knitting the inside selvage of the reinforcing areas, to knit longer loops. In the illustrated construction, the relative positions of the auxiliary verge plate rails 492 and 494 are controlled by the spindle nuts normally employed for positioning the inner stops for the splicing carriers normally employed in these machines.

A pair of such splicing carrier spindle nuts is specifically illustrated in Fig. 9 of the drawings,

the left hand nut being designated at 530, and the right hand nut being designated at 532 supported on oppositely threaded portions of a spindle 534. In accordance with the usual practice, the nut 530 has supported thereon one or more stop pins such as that indicated at 536, the nut 532 being similarly arranged to support carrier stop pins such as that indicated at 538. The stop pin 536 is supported in alignment with a carrier stop 540 carried on one of the carrier rods 86, the pin 538 being similarly arranged in the path of movement of a carrier stop 542 on a second carrier rod 86, for traversing splicing carriers. The nut 530 is provided also with an extension 544 which is rigidly connected to the auxiliary verge plate rail 492, the nut 532 being similarly provided with a forward extension 546 which is rigidly connected to the auxiliary verge plate rail 494. With this construction, it will readily be seen that the positions of the auxiliary verge plates 500 and 502 will be adjusted simultaneously with the shifting of the carrier stop pins 536 and 538.

The spindle 534 is racked by mechanism which may be of ordinary description, comprising a pair of ratchets 548 and 550 (see Figs. 9 and 10) which are arranged to be acted upon by pawls 552 and 554 supported on the upper end of a pawl actuating lever 556 pivotally supported at 558 on the machine frame. At its lower end the lever 556 is connected by a link 560 to a cam lever 562 supported on the pivot shaft 438 and fitted with a shiftable roller 564 for engagement with a cam on the cam shaft 50.

The spindle racking mechanism above described, is thrown into and out of operation by connections from the pattern chain 444 of the machine, through connections which include a shifting fork 566 supported on a lengthwise extending control rod 568 in accordance with the usual practice in these machines. As best shown in Fig. 10, pawls 552 and 554 are spaced apart by means of a stop screw 570 to cause only one of these pawls to be in engagement with its ratchet at one time. A tension spring 572 connected between two pawls, acts to maintain the relative position of the pawls. The direction of the racking is controlled through connections well known in the art including a link 574 connected at one end to the pawl 552, and at its other end to bell-crank 576, the other arm of which is connected by a link 578 and a bell-crank 580 to a pattern control rod 582 controlled from the main pattern chain 444 of the machine.

In order that the operation of applicant's machine may be readily understood, detail views have been made of the several operating cams through which motions are imparted which are new or distinctively different from those employed on Cotton type full-fashioned machines. It will be understood that the needle motion of the machine has been altered only so far as necessary to compensate for the removal of the usual dividing sinkers, together with the dividing operation ordinarily performed by these elements. The usual Coulier motion of the machine, as above noted, is employed to impart reciprocating movements to the yarn carriers and to the sinker guard and release cams of the present machine. The additional Coulier motion employed for reciprocating the hydraulic pistons 150, is cammed in such a manner as to provide an accelerating and decelerating motion of the assembly including pistons 150 at each end of the traverse, in order to reduce so far as possible the power re-

quired for moving this relatively heavy mechanism. In order to provide for such acceleration and deceleration, a Coulier stroke is employed for reciprocating the pistons 150 which is considerably in excess of that employed for reciprocating the yarn carriers. Inasmuch as the actual release of the sinkers is controlled by release cams 316 and 320 which travel at a uniform rate during the traverse, the rate of travel of the pistons 150 is unimportant, except that a sufficient lead must be maintained to insure the projection of the sinkers against the trailing release cam. This lead during the major portion of the traverse may be designated by the distance X, as shown in Figs. 19 and 20, but due to the decelerating motion at the end of the traverse, is later reduced to distance Y, as shown in Fig. 21.

In order that the operation of applicant's machine may be more readily understood, the several operating cams have been marked to show the successive positions of the actuating cam rollers with relation to these cams for a number of positions of the machine during the knitting of a course, these positions being lettered from A to H' inclusive. The operation of the machine will be described with relation to these successive positions of the machine. The machine parts have been specifically illustrated in a starting position of the machine at the beginning of the traversing stroke of the yarn carriers from left to right. The needles as particularly shown in Figs. 1 and 10, are located in the normal yarn sinking position, the vertical position being controlled by the vertical motion needle cam 70, the in-and-out position of the needles with relation to the press edge being at this time controlled by the engagement of the stop pin 466 with the detent lever 462 as shown in Fig. 10. The catch bar 360 of the machine is in its low retracted position, as best shown in Fig. 16, and is determined by the A position of its vertical motion cam 382 (Fig. 4), and in-and-out motion cam 374 (Fig. 6). The verge plates 390 will at this time be in an adjusted position which is determined by the angular position of the pattern controlled face cam disk 406 (see Figs. 10 to 12 inclusive). It will be understood that this position of the verge plate remains unchanged during the subsequent rotation of the machine cam shaft 50 to form the knitted course. The sinker guard and release cam rail 294 is at this time in its low position as determined by the A position of its vertical motion cam 310 (Fig. 5). The guard cams 314 are located in operating position in front of the slider butts 122, and occupy the position shown particularly in Fig. 18. The active yarn carriers are in their positions at the extreme left of each knitting section. For this position of the parts, the right hand release cam 316 associated with each section, is still exposed, the left hand release cam 320 being still in its retracted position. For this position of the parts, the pistons 150 are located in their positions to the extreme left, the valve positions at this time having been reversed by the engagement of cam 268 on the hydraulic piston traversing slide 226 with the pawl plunger 250 (see Figs. 7 and 8), so that fluid pressure is being admitted to the left hand end, and is being exhausted from the right hand end of each hydraulic cylinder 138. The position of the sinkers, guard and release cams, and pistons for each of successive positions A, B, C, D and E, are specifically shown in corresponding Figs. 18 to 22 inclusive.

As the cam shaft 50 and associated parts of 75

the machine are now rotated from the A to the B position, the positions of the needles 52, catch bar 360 and verge plate 390 remain unchanged. The sinker guard and release cam rail 294 remains in its low position, but has started its traversing stroke to the right. The positions of the traversing mechanisms for position B is particularly illustrated in Fig. 19, in which the pistons 150 have established a lead indicated at X over the active yarn carrier 84 and guard cams 314. The trailing or left hand release cam 320 has now been moved out of its operating position by the engagement of actuating member 342 with pin 350 to control the projecting movement of the sinkers.

Continued rotation of the machine to a B' position, causes the catch bar 360 to be lowered to a position in which the rear lip of the catch bar is located below the level of the sinker butts 102. Prior to the movement of the leading ends of the guard cams 314 into the next adjacent sections to the right, the actuating member 350 will have engaged with the pin 346 associated with the leading release cam 316 to retract this cam to inoperative position.

During continued rotation of the machine to the C position, the traversing stroke of the Coulier motions continues as shown in Fig. 20. At this time the catch bar 360 starts to move forwardly below the sinker butts 102.

During continued rotation of the machine to the D position shown particularly in Fig. 21, the traversing stroke of the Coulier motions still continues, the movement of the pistons 150, however, having been slowed down, reducing the lead of the pistons 150 with relation to the yarn carriers and sinker guard and release cams to distance Y.

During rotation of the machine to the E position shown particularly in Fig. 22, the yarn carriers 84, the pistons 150 and the sinker guard and release cam rail 294 with its associated cams will have reached the right hand limit of their traversing stroke. At this point the needles start their downward movement to the press. Also prior to this time, the needle in-and-out motion cam 80 will have taken over the control of the in-and-out motion of the needles. The catch bar now moves upwardly to engage the sinker butts 102 in the slot 362. Also the sinker guard and release cam rail 294 is moved upwardly to permit rearward movement of the slider butts 122 beneath the guard and release cams.

During rotation of the machine to the F position, the needles move to press. The detent lever 462 is moved rearwardly to its inoperative position shown in Fig. 30, by the engagement of the roller 476 with the high portion of the operating cam 480 as shown in Fig. 30. The catch bar 360 now controlling the positions of the sinkers 90 and 92, moves rearwardly with the needles during the pressing operation, to prevent undue stretching of the loops or excessive strain on the needle shanks.

During rotation of the machine to the G position, the needles now move forwardly and down to draw the kinked yarn off the noses of the sinkers in the usual manner. The catch bar moves rearwardly, withdrawing the sinkers. The traversing parts of the machine remain stationary.

During continued rotation of the machine to the H' position, the needles move rearwardly toward the press to knock over the sunk loops against the knockover bits in the usual manner.

The detent lever is again moved outwardly as the roller 476 rides off the high portion of the cam 488, this outward position of the detent lever 462 being determined by the engagement of latch 462 with stop lug 486 as shown in Fig. 10 of the drawings. At this time the catch bar moves the sinkers forwardly and then back in the usual manner, for the correct formation of the selvage.

During rotation of the machine to the H' position, the needles continue to move in the usual manner upwardly toward the Coulier position. The catch bar 360 and the sinkers are now withdrawn to their fully retracted position preparatory for the next yarn measuring operation, and the catch bar 360 is again lowered to the position shown in Fig. 16.

In the subsequent operation of the machine to knit the next course, the operations above described are repeated with the traversing mechanism controlled by the Coulier cams moving from right to left.

It will be understood that the invention is not limited to the specific embodiment shown, and that various deviations may be made therefrom without departing from the spirit and scope of the appended claims.

What is claimed is:

1. In a knitting machine having knitting instrumentalities including needles, implements cooperating therewith to form knitted loops, and means for feeding yarn to said instrumentalities, the combination of fluid pressure actuated means for serially actuating certain of said instrumentalities to kink the feeding yarn, and means for controlling the rate of serial actuation and the rate of movement of each individually actuated instrumentality to produce a knitting wave of predetermined form.

2. In a knitting machine having knitting instrumentalities including a needle series, a series of implements cooperating therewith to form knitted loops, and means for feeding yarn to said instrumentalities, the combination of fluid pressure actuated means for serially actuating certain of said instrumentalities to kink the feeding yarn including connections through which fluid pressure is applied to each of said certain instrumentalities, a fluid pressure control element movable to admit fluid pressure serially to said connections, and operating means having a mechanical connection with said fluid pressure control element for traversing the same.

3. In a knitting machine having knitting instrumentalities including a needle series, a series of implements cooperating therewith to form knitted loops, and means for feeding yarn to said instrumentalities, the combination of fluid pressure actuated means for serially actuating certain of said instrumentalities to kink the feeding yarn including a fluid pressure cylinder extending lengthwise of the needle series, connections from said cylinder through which fluid pressure is applied to actuate each of said certain instrumentalities, a piston in the cylinder movable to admit fluid pressure serially to said connections, and mechanical connections including a piston rod attached to the piston for traversing the piston.

4. In a knitting machine having knitting devices including a needle series, a series of individually movable yarn measuring sinkers cooperating therewith, and means for feeding yarn to the sinkers, the combination of fluid

pressure actuated means for serially projecting the sinkers to kink the feeding yarn including a fluid pressure cylinder extending lengthwise of the needle series, means for admitting fluid pressure to said cylinder, connections from said cylinder at spaced intervals along its length through which fluid pressure is applied to project each of said sinkers, a piston movable in said cylinder to admit fluid pressure serially to said connections, a drive for said yarn feeding means, and driving means for said piston arranged to produce a lead in the movement of the piston with relation to said yarn feeding means during movement in each direction.

5. In a knitting machine having knitting devices including a needle series, a series of yarn measuring sinkers cooperating therewith, and means for feeding yarn to the sinkers, the combination of fluid pressure actuated means for serially projecting the sinkers including a fluid pressure cylinder extending lengthwise of the needle series, means for admitting fluid pressure to said cylinder, connections from said cylinder at spaced intervals and staggered with relation to one another along its length through which fluid pressure is applied to project each of said sinkers, and a piston movable in said cylinder to admit fluid pressure serially to said connections, and actuating connections including a piston rod connected to said piston for reciprocating the same.

6. In a flat knitting machine having knitting devices including a series of needles movable as a unit, a series of yarn measuring sinkers cooperating therewith, and means for feeding yarn to the sinkers, the combination of fluid pressure actuated means for serially projecting the sinkers including a fluid pressure cylinder extending lengthwise of the needle series, means for admitting fluid pressure to said cylinder, connections from said cylinder at spaced intervals along its length through which fluid pressure is applied to project each of said sinkers, a piston movable in said cylinder to admit fluid pressure serially to said connections, a Coulier drive for said yarn feeding means, and a second Coulier drive and mechanical connections between said second Coulier drive and the piston for reciprocating said piston.

7. In a knitting machine having knitting devices including a needle series, a series of yarn measuring sinkers cooperating therewith, and means for feeding yarn to the sinkers, the combination of fluid pressure actuated means for serially projecting the sinkers including a fluid pressure cylinder extending lengthwise of the needle series, a series of sinker actuating pins located at spaced intervals along the length of said cylinder and arranged to be acted upon by fluid pressure, a piston and mechanical connections including a piston rod attached to the piston for traversing the piston in said cylinder, fluid pressure admission and exhaust means located at opposite ends of the cylinder, and means for controlling said pressure and exhaust means to exhaust fluid pressure from the leading side of said piston and to admit fluid pressure to the trailing side of said piston whereby fluid pressure is applied to serially actuate said pins.

8. In a knitting machine having knitting devices including a needle series, a series of yarn measuring sinkers cooperating therewith, and means for feeding yarn to the sinkers, the combination of fluid pressure actuated means for

serially projecting the sinkers including a fluid pressure cylinder extending lengthwise of the needle series, connections located at spaced intervals and staggered with relation to one another along the length of the cylinder through which fluid pressure is applied to advance each of said sinkers, a piston and means for traversing the piston in the cylinder, fluid pressure admission and exhaust means located at each end of the cylinder, and means for controlling said pressure admission and exhaust means to exhaust fluid pressure from the leading side of said piston and to admit fluid pressure to the trailing side of said piston for serially applying said fluid pressure through said connections to project the sinkers.

9. In a knitting machine having knitting devices including a needle series, a series of yarn measuring sinkers cooperating therewith, and means for feeding yarn to the sinkers, the combination of fluid pressure actuated means for serially advancing the sinkers including a fluid pressure cylinder extending lengthwise of the needle series, connections at spaced intervals along the length of the cylinder through which fluid pressure is applied to advance each of said sinkers, pressure and exhaust valve means at both ends of the cylinder, a piston in the cylinder, a piston rod attached thereto, means on the piston rod for traversing the piston in the cylinder, and means operable at each end of the piston traversing stroke to shift said valve means to admit fluid pressure to the trailing side of the piston and to exhaust fluid pressure from the leading side of the piston.

10. In a knitting machine having knitting devices including a needle series, a series of yarn measuring sinkers cooperating therewith, and means for feeding yarn to the sinkers, the combination of fluid pressure actuated means for serially advancing the sinkers including a fluid pressure cylinder extending lengthwise of the needle series, connections at spaced intervals along the length of the cylinder through which fluid pressure is applied to advance each of said sinkers, pressure and exhaust valve means at both ends of the cylinder, a piston in the cylinder, driving means including a Coulier arm for traversing the piston, and connections controlled from said Coulier arm for shifting said valve means at each end of the Coulier stroke to admit fluid pressure to the trailing side of the piston and to exhaust fluid pressure from the leading side of the piston.

11. In a knitting machine having knitting devices including a needle series, a series of yarn measuring sinkers cooperating therewith, and means for feeding yarn to the sinkers, the combination of fluid pressure actuated means for serially advancing the sinkers including a fluid pressure cylinder extending lengthwise of the needle series, connections at spaced intervals along the length of the cylinder through which fluid pressure is applied to advance each of said sinkers, a pressure valve and an exhaust valve at each end of the cylinder, means including a rotatable shaft and connections therefrom for controlling said valves to admit fluid pressure to one end of said cylinder and to exhaust fluid pressure from the other end of said cylinder and vice versa, a piston and driving means for traversing the piston in the cylinder including means operable at each end of the piston stroke to actuate said shaft to admit fluid pressure to the

trailing side of the piston and to exhaust fluid pressure from the leading side of the piston.

12. In a knitting machine having knitting devices including a needle series, a series of yarn measuring sinkers cooperating therewith, and means for feeding yarn to the sinkers, the combination of fluid pressure actuated means for serially advancing the sinkers including a fluid pressure cylinder extending lengthwise of the needle series, a series of sinker actuating pins supported in staggered relation along the length of the cylinder and arranged to be acted upon by fluid pressure, and means including a piston traversable in the cylinder for admitting fluid pressure to successively actuate said pins.

13. In a flat knitting machine having knitting devices including a needle series, a series of yarn measuring sinkers cooperating therewith, and means for feeding yarn to the sinkers, the combination of fluid pressure actuated means for serially advancing the sinkers including a fluid pressure cylinder extending the length of the needle series, and means for admitting fluid pressure to said cylinder, a series of pins slidably supported in holes formed at spaced intervals along the length of the cylinder to be acted upon by fluid pressure in the cylinder, a series of pins arranged in axial alignment with and abutting the ends of said first series of pins, and a series of sinker actuated sliders arranged to be acted upon by said latter series of pins.

14. In a flat knitting machine having knitting devices including a needle series, a series of yarn measuring sinkers cooperating therewith, and means for feeding yarn to the sinkers, the combination of fluid pressure actuated means for serially advancing the sinkers including a fluid pressure cylinder extending the length of the needle series having formed at spaced intervals along its length a series of holes, a series of pins slidably supported in said holes to be acted upon by fluid pressure in the cylinder, said pins having enlarged heads supported within enlarged portions of said holes, a second series of pins arranged in axial alignment with and abutting the heads of said first series of pins to be acted upon by said first series of pins to advance the sinkers, and stop surfaces arranged for engagement with said heads to limit movement of said first series of pins in both directions.

15. In a flat knitting machine having knitting devices including a needle series, a series of yarn measuring sinkers cooperating therewith, and means for feeding yarn to the sinkers, the combination of fluid pressure actuated means for serially advancing the sinkers including a fluid pressure cylinder extending the length of the needle series having formed at spaced intervals along its length a series of holes, a series of pins slidably supported in said holes to be acted upon by fluid pressure in the cylinder, said pins having enlarged heads supported within enlarged portions of said holes, a second series of pins arranged in axial alignment with and abutting the heads of said first series of pins to be acted upon by said first series of pins to advance the sinkers, stop surfaces arranged for engagement with said heads to limit movement of said series of pins in both directions, and means to collect fluid forced past the pins of said first series into the enlarged portions of said holes.

16. In a flat knitting machine having knitting devices including a needle series, a series of yarn measuring sinkers cooperating therewith, and

means for feeding yarn to the sinkers, the combination of fluid pressure actuated means for serially advancing the sinkers including a series of pins, each having at the forward end thereof an enlarged head, a support having holes within which said pins are slidably supported to project individual sinkers and enlarged portions of said holes to receive the pin heads, and means for admitting fluid pressure to serially actuate said pins, a second series of pins slidably supported in axial alignment with and abutting the heads of said first series of pins for advancing the sinkers, and means to collect fluid forced past the pins of said first series into the enlarged portions of said holes.

17. In a knitting machine having knitting instrumentalities including a needle series, a series of implements cooperating therewith to form knitted loops, and means for feeding yarn to said instrumentalities, the combination of fluid pressure actuated means for serially actuating certain of said instrumentalities to kink the feeding yarn, and means for controlling the yarn kinking movement of said certain instrumentalities including means to retard the movement of each of said certain instrumentalities under the influence of said pressure actuated means in accordance with a knitting wave.

18. In a knitting machine having knitting instrumentalities including a needle series, a series of implements cooperating therewith to form knitted loops, and means for feeding yarn to said instrumentalities, the combination of fluid pressure actuated means for serially actuating certain of said instrumentalities to kink the feeding yarn, and means for controlling the yarn kinking movement of said certain instrumentalities including guard and release cam means relatively movable lengthwise of the needle series to release said certain instrumentalities serially while acted upon by said fluid pressure actuated means, and means for imparting relative movement to said certain instrumentalities and to said cam means to release said certain instrumentalities in accordance with a knitting wave.

19. In a flat knitting machine having knitting devices including a needle series, a series of yarn measuring sinkers cooperating therewith, and means for feeding yarn to the sinkers, the combination of fluid pressure actuated means for advancing the sinkers, and means for controlling the advance of the sinkers under the influence of said fluid pressure actuated means including means to release the sinkers serially while acted upon by said fluid pressure actuated means.

20. In a flat knitting machine having knitting devices including a needle series, a series of yarn measuring sinkers cooperating therewith, and means for feeding yarn to the sinkers, the combination of fluid pressure actuated means for advancing the sinkers, and means for controlling the advance of the sinkers by said fluid pressure actuated means, including locking means to prevent the advance of the sinkers from the retracted position, and means to release the sinkers serially in accordance with a predetermined form of knitting wave.

21. In a flat knitting machine having knitting devices including a needle series, a series of yarn measuring sinkers cooperating therewith, and means for feeding yarn to the sinkers, the combination of fluid pressure actuated means for advancing the sinkers, and means for controlling the advance of the sinkers by said fluid pressure actuated means including a guard cam operative

to prevent the advance of the sinkers from their retracted position, and a release cam shaped to release the sinkers serially in accordance with a predetermined form of knitting wave.

5 22. In a flat knitting machine having knitting devices including a needle series, a series of yarn measuring sinkers cooperating therewith, and means for feeding yarn to the sinkers, the combination of fluid pressure actuated means for advancing the sinkers, and means for controlling the advance of the sinkers by said fluid pressure actuated means including guard and release cam means movable lengthwise of the sinker series to release the sinkers serially in accordance with a knitting wave.

10 23. In a flat knitting machine having knitting devices including a needle series, a series of yarn measuring sinkers cooperating therewith, and means for feeding yarn to the sinkers, the combination of fluid pressure actuated means for advancing the sinkers, and means for controlling the advance of the sinkers by said fluid pressure actuated means including guard and release cam means movable lengthwise of the sinker series, and means to traverse said guard and release cam means to release the sinkers in accordance with a knitting wave.

15 24. In a flat knitting machine having knitting devices including a needle series, a series of yarn measuring sinkers cooperating therewith, and means for feeding yarn to the sinkers, the combination of fluid pressure actuated means for advancing the sinkers, and sinker guard and release cam means for controlling the advance of the sinkers by said fluid pressure actuated means including a sinker guard cam extending the length of the sinker series and movable lengthwise with relation thereto, release cams at each end of said guard cam supported to move therewith and shaped to release the sinkers in accordance with a predetermined form of knitting wave, means for traversing said guard and release cams to serially release the sinkers, and means to render the leading release cam inoperative and the trailing release cam operative to control the advance of the sinkers for each direction of traverse of said guard and release cams.

20 25. In a multiple section flat knitting machine having associated with each knitting section, knitting devices including a needle series, a series of yarn measuring sinkers cooperating therewith, and means for feeding yarn to the sinkers, the combination of fluid pressure actuated means for advancing the sinkers, and guard and release cam means associated with each knitting section for controlling the advance of the sinkers by said fluid pressure actuated means including a guard cam extending substantially the length of the sinker series and movable lengthwise with relation thereto, release cams at each end of said guard cam supported to move therewith and shaped to release the sinkers in accordance with a predetermined form of knitting wave, a control butt associated with each sinker arranged for engagement with said guard and release cams, means operative to move said guard cams from a position opposite one knitting section to a position opposite an adjacent knitting section, and means to render each leading release cam inoperative and each trailing release cam operative to control the advance of the sinkers for each direction of traverse of said guard and release cams.

26. In a flat knitting machine having knitting devices including a needle series, a series of yarn measuring sinkers cooperating therewith, and

means for feeding yarn to the sinkers, the combination of fluid pressure actuated means for advancing the sinkers, and means for controlling the advance of the sinkers including a control butt associated with each sinker, a guard cam extending substantially the length of the sinker series, a release cam at each end of the guard cam, a support for said guard and release cams, means for traversing said support and cams lengthwise of the sinker series, means for moving the leading release cam to inoperative position on the support and the trailing release cam to operative position for each direction of traverse of the support, means for retracting the sinkers, and means operative during said retracting movement of the sinkers to move the support and cams mounted thereon out of the path of movement of the sinker control butts.

27. In a multiple section flat knitting machine having associated with each knitting section, knitting devices including a needle series, a series of yarn measuring sinkers cooperating therewith, and means for feeding yarn to the sinkers, the combination of fluid pressure actuated means for advancing the sinkers, and means for controlling the advance of the sinkers including a control butt associated with each sinker, a guard cam associated with each knitting section extending substantially the length of the sinker series, a release cam at each end of the guard cam, a support for said guard and release cams extending along the length of the machine, means for traversing said support and cams lengthwise of the machine to move each guard cam from a position in front of one knitting section to a position in front of an adjacent knitting section, means for moving the leading release cam associated with each guard cam to inoperative position on the support and the trailing release cam to an operative position on the support for each direction of traverse of the support, means for retracting the sinkers, and means operative during said retracting movement of the sinkers to move the support and cams mounted thereon out of the path of movement of the sinker control butts.

28. In a multiple section flat knitting machine having associated with each knitting section, knitting devices including a needle series, a series of yarn measuring sinkers cooperating therewith, and means for feeding yarn to the sinkers, the combination of fluid pressure actuated means for advancing the sinkers, and means for controlling the advance of the sinkers including a control butt associated with each sinker, guard and release cam means associated with each knitting section comprising a guard cam extending substantially the length of the sinker series and at each end thereof a release cam to release the sinkers acted upon by said fluid pressure actuated means, a support for said guard and release cams extending along the length of the machine, means for traversing said support and cams lengthwise of the machine to move each guard cam from a position in front of one knitting section to a position in front of an adjacent knitting section, so that each trailing release cam is operative to release the sinkers acted upon by said fluid pressure means in accordance with a knitting wave, means for retracting the sinkers, and means operative during said retracting movement of the sinkers to move the support and cams mounted thereon out of the path of movement of the sinker control butts.

29. In a multiple section flat knitting machine having associated with each knitting section, 75

knitting devices including a needle series, a series of yarn measuring sinkers cooperating therewith, and means for feeding yarn to the sinkers, the combination of fluid pressure actuated means for advancing the sinkers, and means for controlling the advance of the sinkers including a control butt associated with each sinker, a guard cam associated with each knitting section substantially the length of the sinker series, a support for said guard cams extending along the length of the machine, a curved release cam at each end of each guard cam for releasing the sinkers serially in accordance with a knitting wave, articulate guideways on the support in which said release cams are movable between projecting operative and retracting inoperative positions, means for traversing said support and cams lengthwise of the machine to move each guard cam from a position in front of one knitting section to a position in front of an adjacent knitting section, pins on the release cams, and spring-seated actuating members located between adjacent sections in the path of said pins operative at the beginning of each traversing movement of said support to move the leading release cam associated with each guard cam to inoperative position, and the trailing release cam to an operative position on the support, means for retracting the sinkers, and means operative during said retracting movement of the sinkers to move the support and cams mounted thereon out of the path of movement of the sinker control butts.

30. In a flat knitting machine having knitting devices including a series of needles, a series of 35 yarn measuring sinkers associated therewith, and means for feeding yarn to the sinkers, the combination of fluid pressure actuated means for advancing the sinkers including a fluid pressure cylinder, outlets spaced along the length of said 40 cylinder through which fluid pressure is applied to advance individual sinkers, a piston traversable in the cylinder, and means for admitting fluid pressure to the trailing side of the piston during its traverse in each direction, means for 45 controlling the advance of the sinkers by said fluid pressure actuated means including traversable guard and release cam means operable to prevent the advance of the sinkers from retracted position and to release the sinkers serially in 50 a knitting wave, means for traversing said guard and release cam means, and means for traversing said piston.

31. In a flat knitting machine having knitting devices including a series of needles, a series of 55 yarn measuring sinkers associated therewith, and means for feeding yarn to the sinkers, the combination of fluid pressure actuated means for advancing the sinkers including a fluid pressure cylinder, outlets spaced along the length 60 of said cylinder through which fluid pressure is applied to advance individual sinkers, a piston traversable in the cylinder, and means for admitting fluid pressure to the trailing side of the piston during its traverse in each direction, means for 65 controlling the advance of the sinkers by said fluid pressure actuated means including traversable guard and release cam means operable to prevent the advance of the sinkers from retracted position and to release the sinkers serially in a knitting wave, means for traversing said guard and release cam means, means for traversing said piston operable to maintain a lead with relation to the guard and release cam whereby fluid pressure is admitted successively

to said outlets prior to the release of the associated sinkers.

32. In a flat knitting machine having knitting devices including a series of needles movable as a unit, a series of yarn measuring sinkers cooperating therewith, and means for feeding yarn to the sinkers, the combination of a verge plate, means for advancing the sinkers against the verge plate to kink yarn against the needle shanks, and means for adjusting loop length which comprises a support on which the verge plate is adjustable in the direction of sinker movement, means for shifting the verge plate to the position of desired adjustment, and control means for rendering said shifting means operative to move the verge plate to said adjusted position.

33. In a flat knitting machine having knitting devices including a series of needles movable as a unit, a series of yarn measuring sinkers cooperating therewith, the combination of a verge plate, means for advancing the sinkers serially against the verge plate to kink yarn against the needle shanks, means for adjusting loop length which comprises a support on which the verge plate is adjustable lengthwise of the sinker series, cam and follower surfaces rendered operative by said lengthwise adjustment to adjust the position of the verge plate forwardly or back in the direction of sinker movement, and means for adjusting the position of the verge plate lengthwise of the sinker series.

34. In a flat knitting machine having knitting devices including a series of needles movable as a unit, a series of yarn measuring sinkers cooperating therewith, the combination of a verge plate, means for advancing the sinkers serially against the verge plate to kink yarn against the needle shanks, means for adjusting loop length which comprises wedge-shaped surfaces on the verge plate, and supporting means including cooperating stationary wedge-shaped cams whereby lengthwise adjustment of the verge plate will effect a corresponding adjustment of the verge plate in the direction of sinker movement.

35. In a flat knitting machine having knitting devices including a series of needles movable as a unit, a series of yarn measuring sinkers cooperating therewith, and means for feeding yarn to the sinkers, the combination of fluid pressure actuated means for advancing the sinkers serially to measure yarn, means for positively limiting said advancing movement to determine loop length, and means for varying said limit of advance of the sinkers to vary loop length.

36. In a flat knitting machine having knitting devices including a series of needles movable as a unit, a series of yarn measuring sinkers cooperating therewith, and means for feeding yarn to the sinkers, the combination of a verge plate, fluid pressure actuated means to advance the sinkers serially against the verge plate, and means to effect adjustment of loop length which comprises means for adjusting the position of the verge plate in the direction of sinker movement.

37. In a flat knitting machine having knitting devices including a series of needles movable as a unit, a series of yarn measuring sinkers cooperating therewith, and means for feeding yarn to the sinkers, the combination of fluid pressure actuated means for advancing the sinkers, guard and release cam means traversable lengthwise of the sinker series to release the sinkers acted upon by said fluid pressure means in accordance

with a knitting wave, and a verge plate to limit the advancing movement of the sinkers.

38. In a flat knitting machine having knitting devices including a series of needles movable as a unit, a series of yarn measuring sinkers cooperating therewith, and means for feeding yarn to the sinkers, the combination of fluid pressure actuated means for advancing the sinkers, guard and release cam means traversable lengthwise of the sinker series to release the sinkers acted upon by said fluid pressure means in accordance with a knitting wave, means for limiting the advance of the sinkers to determine loop length, and means for varying the limit of said advancing movement of the sinkers to vary the loop length.

39. In a flat knitting machine having knitting devices including a series of needles movable as a unit, a series of yarn measuring sinkers cooperating therewith, and means for feeding yarn to the sinkers, the combination of a needle knitting motion including means for locating the needles in a predetermined yarn sinking position, means to advance the sinkers serially to kink yarn against the needle shanks, means for limiting said advancing movement to determine loop length, a pattern mechanism for the machine, and means controlled thereby for varying said limit of advancing movement to adjust loop length.

40. In a flat knitting machine having knitting devices including a series of needles movable as a unit, a series of yarn measuring sinkers cooperating therewith, and means for feeding yarn to the sinkers, the combination of a needle knitting motion including means for locating the needles in a predetermined yarn sinking position, fluid pressure actuated means to advance the sinkers serially to kink yarn against the needle shanks, means for positively limiting the advance of the individual sinkers by said fluid pressure actuated means, and means to vary the limit of advancing movement of said sinkers to vary loop length.

41. In a flat knitting machine having knitting devices including a series of needles movable as a unit, a series of yarn measuring sinkers cooperating therewith, and means for feeding yarn to the sinkers, the combination of means for serially advancing the sinkers to kink yarn against the needle shanks, means for limiting the advancing movement of the sinkers to determine loop length, a pattern mechanism for the machine and means controlled thereby to vary the limit of advancing movement of selected sinkers of the series to produce loops of different length along the length of the needle series.

42. In a flat knitting machine having knitting devices including a series of needles movable as a unit, a series of yarn measuring sinkers cooperating therewith, and means for feeding yarn to the sinkers, the combination of a needle motion including means for locating the needles in a predetermined yarn sinking position, fluid pressure actuated means to advance the sinkers serially to kink yarn against the needle shanks, means for positively limiting the advance of certain of said sinkers with relation to the needles under the influence of said fluid pressure actuated means to produce loops of a predetermined length, and means for limiting the advance of certain other of said sinkers with relation to the needle shanks under the influence of said fluid pressure actuated means operative to produce a different loop length.

43. In a flat knitting machine having knitting devices including a series of needles movable as a unit, a series of yarn measuring sinkers cooperating therewith, and means for feeding yarn to the sinkers, the combination of a needle motion including means operable to position the needles in either of two alternative yarn sinking positions, means for advancing the sinkers serially to kink yarn against the needle shanks, a verge plate adjustable to vary the limit of advance of the sinkers, additional sinker stop means operable to stop the advance of a selected number of the sinkers in said series, control means operative to position the needles in one of said yarn sinking positions and to adjust the verge plate relatively thereto to determine the length of loop measured by all of said sinkers, and means acting when rendered operative to position the needles in the other of said alternative yarn sinking positions and to effect an adjustment of said verge plate whereby said additional sinker stop means are rendered operative to limit the advance of said selected number of sinkers, said verge plate acting to determine loop length only of the remaining sinkers.

44. In a flat knitting machine having knitting devices including a series of needles movable as a unit, a series of yarn measuring sinkers cooperating therewith, and means for feeding yarn to the sinkers, the combination of a needle knitting motion including means for positioning the needles in either of two alternative retracted and advanced yarn sinking positions, means for advancing the sinkers serially to kink yarn against the needle shanks, a verge plate having alternative retracted and advanced sinker stop positions, additional sinker stop means operable to limit the advance of a selected number of the sinkers in said series, the sinkers having stop surfaces cooperating with said verge plate, and additional stop surfaces cooperating with said additional stop means, means normally operative to position the needles in said retractive yarn sinking position and to position the verge plate in said retracted sinker stop position to determine the length of loop measured by all the sinkers, and means for shifting the verge plate to its advanced sinker stop position and for positioning the needles in said advanced yarn sinking position to cause said additional sinker stop means to limit the advance of selected sinkers engaged thereby to form normal size loops, and the verge plate to limit the advance of the remaining sinkers only to form larger loops.

45. In a flat knitting machine having knitting devices including a series of needles movable as a unit, a series of yarn measuring sinkers cooperating therewith, and means for feeding yarn to the sinkers, the combination of a needle knitting motion including means operable to position the needles in a predetermined yarn sinking position, means for advancing the sinkers serially to kink yarn against the needle shanks, a verge plate extending the length of the sinker series, a pair of additional verge plates each extending over a portion only of the sinker series to limit the advance of a selected number of sinkers of the series and relatively adjustable lengthwise of the sinker series, the sinkers comprising half the sinker series having stop surfaces cooperating with said first-mentioned verge plate and stop surfaces cooperating with one additional verge plate, the sinkers comprising the other half of the sinker series having stop sur-

faces cooperating with said first-mentioned verge plate and stop surfaces cooperating with the other of said additional verge plates, means for relatively positioning the needles in yarn sinking position, the verge plate, and said additional verge plates to cause said additional verge plates to limit the advance of a selected number of sinkers in the series, and to form loops of one length and to cause said first-mentioned verge plate to limit the advance of the remaining sinkers only to measure loops of a greater length, and means for adjusting the lengthwise position of each of said additional verge plates to vary the number of sinkers engaged thereby.

46. In a flat knitting machine having knitting devices including a series of needles movable as a unit, a series of yarn measuring sinkers cooperating therewith, and means for feeding yarn to the sinkers, the combination of a needle motion including means to position the needles in a predetermined yarn sinking position, means for advancing the sinkers serially to kink yarn against the needle shanks, a verge plate to limit the advance of the sinkers, additional sinker stop means operable to limit the advance of a selected number of sinkers in the series, means for relatively positioning the needles in yarn sinking position, the verge plate and said additional sinker stop means to cause said sinker stop means to limit the advance of selected sinkers to measure loops of one length, and to cause the verge plate to limit the advance of the remaining sinkers only to measure loops of a different length.

47. In a flat knitting machine having knitting devices including a series of needles movable as a unit, a series of yarn measuring sinkers cooperating therewith, and means for feeding yarn to the sinkers, the combination of a needle motion including means to position the needles in a predetermined yarn sinking position, means for advancing the sinkers serially to kink yarn against the needle shanks, a verge plate to limit the advance of the sinkers, additional sinker stop means operable to limit the advance of a selected number of sinkers in the series, means for relatively positioning the needles in yarn sinking position, the verge plate and said additional sinker stop means to cause said sinker stop means to limit the advance of selected sinkers to measure loops of one length, and to cause the verge plate to limit the advance of the remaining sinkers only to measure loops of a different length, and means for adjusting said sinker stop means to vary the number of selected sinkers controlled thereby.

48. In a flat knitting machine having knitting devices including a series of needles movable as a unit, a series of yarn measuring sinkers cooperating therewith, and means for feeding yarn to the sinkers including reinforcing yarn carriers, the combination of a needle motion including means to position the needles in a predetermined yarn sinking position, means for advancing the sinkers serially to kink yarn against the needle shanks, a verge plate to limit the advance of the sinkers, additional sinker stop means operable to limit the advance of a selected number of intermediate sinkers in the series, means for relatively positioning the needles in yarn sinking position, the verge plate and said additional sinker stop means to cause said sinker stop means to limit the advance of selected intermediate sinkers to measure loops of one length and to cause the verge plate to limit the advance of the remaining sinkers only to measure loops of a

greater length, carrier traversing means including inner selvage stops for said reinforcing yarn carriers to feed reinforcing yarn to the sinkers knitting longer loops, and means for varying the position of said stops and for correspondingly adjusting said sinker stop means to vary the number of selected sinkers controlled thereby.

49. In a flat knitting machine having knitting devices including a series of needles movable as a unit, a series of yarn measuring sinkers cooperating therewith, and means for feeding yarn to the sinkers including reinforcing yarn carriers, the combination of a needle motion including means operative to position the needles in either of two alternative retracted or advanced yarn sinking positions, means for advancing the sinkers serially to kink yarn against the needle shanks, a verge plate having alternative retracted and advanced sinker stop positions, a pair of additional verge plates relatively adjustable lengthwise of the sinker series, the sinkers comprising half the sinker series having stop surfaces cooperating with said first-mentioned verge plate and stop surfaces cooperating with one of said additional verge plates, the sinkers comprising the other half of the sinker series having stop surfaces cooperating with said first-mentioned verge plate and stop surfaces cooperating with the other of said additional verge plates, means normally operative to position the needles in said retracted yarn sinking position and to position the verge plate in said retracted sinker stop position to limit the length of loop measured by all the sinkers, means for shifting the verge plate to its advanced sinker stop position and for positioning the needles in said advanced yarn sinking position to cause said additional verge plates to limit the advance of selected sinkers engaged thereby to form normal size loops and to cause the first-mentioned verge plate to limit the advance 40 of the remaining sinkers only to form larger loops, carrier traversing means including inner selvage stops for said reinforcing yarn carriers for feeding reinforcing yarn to the sinkers knitting longer loops, and means for varying the position of said stops and for correspondingly adjusting the position of said additional verge plates to vary the number of selected sinkers controlled thereby.

50. In a flat knitting machine having knitting devices including a needle series, a series of yarn measuring sinkers cooperating therewith, and means for feeding yarn to the sinkers, the combination of fluid actuated means for advancing the sinkers including a fluid pressure cylinder and serially spaced outlets therefrom through which fluid pressure is applied to advance individual sinkers, a piston having a traversing stroke in each direction which extends a substantial distance beyond the end outlet of the series, means for admitting fluid pressure to the trailing side of said piston during traverse in each direction, means for controlling the advance of the sinkers by said fluid pressure actuated means including sinker guard and release cam means traversable to serially release the sinkers actuated by said fluid pressure in a knitting wave, and means for traversing each of said piston and said cam means operative to maintain a lead of the piston with relation to the release cam to admit fluid pressure to actuate each successive sinker prior to the release of said sinker by said cam means.

51. In a flat knitting machine having knitting devices including a needle series, a series of yarn

measuring sinkers cooperating therewith, and means for feeding yarn to the sinkers, the combination of fluid actuated means for advancing the sinkers including a fluid pressure cylinder and serially spaced outlets therefrom through which fluid pressure is applied to advance individual sinkers, a piston having a traversing stroke in each direction which extends a substantial distance beyond the end outlet of the series, means for admitting fluid pressure to the trailing side of said piston during traverse in each direction, means for controlling the advance of the sinkers by said fluid pressure actuated means including sinker guard and release cam means traversable to serially release the sinkers actuated by said fluid pressure in a knitting wave, a coulier mechanism for traversing the guard and release cam means to release the sinkers at a uniform rate, and a separate coulier mechanism for traversing the piston having a gradual take-up and arranged to maintain a substantial lead of the piston with relation to said cam means to admit fluid pressure to actuate each successive sinker prior to the release of said sinker by the release cam.

52. In a flat knitting machine having knitting devices including a series of needles movable as a unit, a series of yarn measuring sinkers cooperating therewith, and means for feeding yarn to the sinkers, the combination of a needle motion including means operative to position the needles in either of two alternative retracted and advanced yarn sinking positions, means for advancing the sinkers serially to kink yarn against the needle shanks, a verge plate having alternative retracted and advanced sinker stop positions corresponding to said retracted and advanced needle yarn sinking positions, additional sinker stop means operable for the advanced position only of said needles and verge plate to limit the advance of a selected number of sinkers in the series, pattern means for shifting the verge plate from one to the other of said retracted and advanced sinker stop positions, and means rendered operative by movement of the verge plate from one to the other of said retracted and advanced positions to position the needles in the corresponding retracted or advanced yarn sinking position.

53. In a flat knitting machine having knitting devices including a series of needles movable as a unit, and individually movable yarn measuring sinkers, the combination of actuating means for the sinkers which comprises an individual slider abutting each sinker to advance the sinker, and provided with a rearwardly extending butt, the butts of adjacent sliders being staggered with relation to each other, and correspondingly staggered actuating pins engaging against said butts.

54. In a flat knitting machine having knitting devices including a series of needles movable as a unit, and individually movable yarn measuring sinkers, the combination of actuating means for the sinkers which comprises an individual slider abutting each sinker to advance the sinker, and provided with a rearwardly extending butt, the butts of adjacent sliders being staggered with relation to each other, correspondingly staggered actuating pins engaging against said butts, and means for successively actuating the pins to serially advance the sinkers.

55. In a flat knitting machine having knitting devices including a series of needles movable as a unit, and individually movable yarn measuring

sinkers, the combination of actuating means for the sinkers which comprises an individual slider abutting each sinker to advance the sinker, said slider being slotted for laterally supporting the associated sinker and provided with a rearwardly extending butt, the butts of adjacent sliders being staggered with relation to one another, and correspondingly staggered actuating pins engaging against said butts.

56. In a flat knitting machine having knitting devices including a series of needles movable as a unit, and individually movable yarn measuring sinkers, the combination of actuating means for the sinkers, which comprises an individual slider abutting each sinker to advance the sinker, actuating pins for the sliders, fluid pressure actuated means for actuating the pins to serially advance the sinkers, guard and release cam means to release the sinkers actuated by said fluid pressure means in a knitting wave, a verge plate to limit the advancing movement of the sinkers, and a catch bar for retracting the sinkers, said sliders having upwardly extending butts for engagement with said guard and release cam means, and rearwardly extending butts for engagement with the actuating pins, said sinkers having stop surfaces for engagement with the verge plate, and downwardly extending butts for engagement with said catch bar.

57. In a flat knitting machine having knitting devices including a series of needles movable as a unit, and individually movable yarn measuring sinkers, the combination of actuating means for the sinkers which comprises an individual slider abutting each sinker, and an actuating pin for the slider, fluid pressure actuated means for actuating said pins to serially advance the sinkers, guard and release cam means to serially release the sinkers actuated by said fluid pressure means, a verge plate, a catch bar, and two additional verge plates operative for limiting the advance of a selected number of sinkers of the series, said sliders having upwardly extending butts for engagement with said guard and release cam means, and rearwardly extending butts for engagement with the actuating pins, the sinkers comprising half of the sinker series having butts for engagement respectively with said first-mentioned verge plate, said catch bar and one of said additional verge plates, the sinkers comprising the other half of said sinker series having butts for engagement respectively with said first-mentioned verge plate, said catch bar and the other of said additional verge plates.

58. In a flat knitting machine having knitting devices including a series of needles movable as a unit, a series of yarn measuring sinkers cooperating therewith, and means for feeding yarn to the sinkers, the combination of a needle motion including means for locating the needles in a predetermined yarn sinking position, fluid pressure actuated means to advance the sinkers serially to kink yarn against the needle shanks, sinker stop means for positively limiting the advance of the sinkers, additional sinker stop means operable to limit the advance of a limited number of sinkers with relation to the needle shanks to produce loops of a different length, a pattern mechanism for the machine, and means controlled thereby for adjusting said first mentioned sinker stop means to vary loop length, and for rendering said additional sinker stop means operative and inoperative.

59. In a flat knitting machine having knitting

devices including a series of needles movable as a unit, a series of yarn measuring sinkers cooperating therewith, and means for feeding yarn to the sinkers, the combination of a needle motion including means for locating the needles in a predetermined yarn sinking position, fluid pressure actuated means to advance the sinkers serially to kink yarn against the needle shanks, sinker stop means for positively limiting the advance of the sinkers, additional sinker stop means operable to limit the advance of a limited number of sinkers with relation to the needle shanks to produce loops of a different length, a pattern mechanism for the machine, means controlled thereby for adjusting said first mentioned sinker stop means to vary loop length, and for rendering said additional sinker stop means operative and inoperative, and means controlled from the pattern mechanism for adjusting said additional sinker stop means to vary the number of sinkers controlled thereby.

60. In a flat knitting machine having knitting devices including a series of needles movable as a unit, a series of yarn measuring sinkers cooperating therewith, and means for feeding yarn to the sinkers, the combination of a needle motion including means for locating the needles in a predetermined yarn sinking position, fluid pressure actuated means to advance the sinkers serially to kink yarn against the needle shanks, a verge plate for positively limiting the advance of the sinkers, additional sinker stop means operable to limit the advance of a limited number of the sinkers with relation to the needle shanks to produce a different loop length, and means for adjusting said additional sinker stop means to vary the number of sinkers controlled thereby.

61. In a flat knitting machine having knitting devices including a series of needles movable as a unit, a series of yarn measuring sinkers cooperating therewith, and means for feeding yarn to the sinkers including reinforcing yarn carriers, the combination of a needle motion including means to position the needles in a predetermined yarn sinking position, means for advancing the sinkers serially to kink yarn against the needle shanks, sinker stop means for positively limiting the advance of the sinkers with relation to the needles to produce loops of a predetermined length, additional sinker stop means operable to limit the advance of a limited number of sinkers in the series to produce loops of a different length, carrier traversing means including inner selvage stops for said reinforcing yarn carriers to feed reinforcing yarn to said limited number of sinkers, and means for varying the position of said stops and for correspondingly adjusting said additional sinker stop means to vary the number of sinkers controlled thereby.

62. In a flat knitting machine having knitting devices including a series of needles movable as a unit, a series of yarn measuring sinkers cooperating therewith, and means for feeding yarn to the sinkers, the combination of a needle motion including means for locating the needles in a normal and alternatively in a second yarn sinking position, means for serially advancing the sinkers to kink yarn against the needle shanks, sinker stop means for limiting the advancing movement of the sinkers to determine loop length, additional sinker stop means acting when rendered operative for limiting the advance of a limited number of said sinkers to produce loops of different lengths from those

produced by the remaining sinkers, and control mechanism arranged to render said latter sinker stop means operative, and simultaneously to locate the needles in the second of said yarn sinking positions.

63. In a multiple section flat knitting machine having associated with each knitting section, knitting devices including a needle series, a series of yarn measuring sinkers cooperating therewith, and means for feeding yarn to the sinkers, the combination of fluid pressure actuated means for serially projecting the sinkers including a series of axially aligned fluid pressure cylinders, one extending along the length of each needle series, connections from each of said cylinders at spaced intervals along their length through which fluid pressure is applied to project each of said sinkers, means for admitting fluid pressure to each of said cylinders, a piston for each of said cylinders movable to admit fluid pressure serially to said connections, and a piston rod extending the length of the several cylinders for traversing the several pistons to admit fluid pressure serially to said connections, said piston rod comprising a series of detachable sections each of equal length with a corresponding cylinder to permit ready removal of individual cylinders.

64. In a multiple section flat knitting machine having associated with each knitting section, knitting devices including a needle series, a series of yarn measuring sinkers cooperating therewith, and means for feeding yarn to the sinkers, the combination of fluid pressure actuated means for serially projecting the sinkers including a series of axially aligned fluid pressure cylinders, one extending along the length of each needle series, connections from each of said cylinders at spaced intervals along their length through which fluid pressure is applied to project each of said sinkers, means for admitting fluid pressure to each of said cylinders, a piston for each of said cylinders movable to admit fluid pressure serially to said connections, a piston rod extending the length of the several cylinders for actuating the pistons, said piston rod comprising a series of abutting sections, and supporting means connecting opposite ends of the piston rod externally of the cylinders to maintain the abutting sections in contacting relation with one another.

65. In a multiple section flat knitting machine having associated with each knitting section, knitting devices including a needle series, a series of yarn measuring sinkers cooperating therewith, and means for feeding yarn to the sinkers, the combination of fluid pressure actuated means for serially advancing the sinkers including a fluid pressure cylinder associated with each section extending lengthwise of the needle series, a piston in each of said cylinders, and means for traversing the pistons, connections at spaced intervals along the length of the cylinder through which fluid pressure is applied to advance each of said sinkers, separate pressure and exhaust valves at both ends of each cylinder, and pressure and exhaust connections therefrom, and means operable at each traversing stroke of said pistons to shift the positions of said valves to admit fluid pressure to the trailing side of each piston, and to exhaust fluid pressure from the leading side of each piston.

66. In a multiple section flat knitting machine having associated with each knitting section, knitting devices including a needle series, a series of yarn measuring sinkers cooperating ther-

with, and means for feeding yarn to the sinkers, the combination of sinker stop means associated with each section for positively limiting said advancing movement of the sinkers to determine loop length, means for positioning said sinker stop means of the several knitting sections to vary the limit of advance of the sinkers to vary loop length, and control means acting on said positioning means for simultaneously effecting identical adjustments of loop length in the several knitting sections.

67. In a multiple section flat knitting machine having associated with each knitting section, knitting devices including a needle series, a series of yarn measuring sinkers cooperating therewith, and means for feeding yarn to the sinkers, the combination of a verge plate extending the length of the several sections and including sinker stop surfaces associated with each knitting section, means for advancing the sinkers against the verge plate to kink yarn against the needle shanks, and means for adjusting loop length which comprises means for positioning said verge plate stop surfaces for each of the several sections, and control means acting on said positioning means for simultaneously effecting identical adjustments of loop length over the several knitting sections.

68. In a multiple section flat knitting machine having associated with each knitting section, knitting devices including a needle series, a series of yarn measuring sinkers cooperating therewith, and means for feeding yarn to the sinkers, the combination of a verge plate including sinker stop surfaces associated with each knitting section, fluid pressure actuating means to advance the sinkers serially against said stop surfaces, and means to effect adjustment of loop length which comprises means for adjusting the positions of said stop surfaces of the verge plate in the direction of sinker movement simultaneously on all of said knitting sections.

69. In a multiple section flat knitting machine having associated with each knitting section, knitting devices including a needle series, a series of yarn measuring sinkers cooperating therewith, and means for feeding yarn to the sinkers, the combination of a verge plate including sinker stop surfaces associated with each knitting section, means for advancing the sinkers against the verge plate to kink yarn against the needle shanks, and means for adjusting loop length which comprises means for adjusting the position of the verge plate, a pattern mechanism for the machine, and connections controlled thereby for actuating said adjusting means.

70. In a multiple section flat knitting machine having associated with each knitting section, knitting devices including a needle series, a series of yarn measuring sinkers cooperating therewith, and means for feeding yarn to the sinkers, the combination of fluid pressure actuated means for advancing the sinkers, a verge plate, means for limiting the advance of the sinkers with relation to the needles under the influence of said fluid pressure actuated means, means for adjusting the position of the verge plate to effect a simultaneous adjustment of loop length on all the knitting sections, a pair of additional stop bars associated with each knitting section arranged to limit the advance of selected sinkers only to produce loops of a different length, and means for shifting the bars of each pair relatively to each other lengthwise of the machine to vary simultaneously and in like manner the

number of selected sinkers stopped by said bars in each of the several sections.

71. In a flat knitting machine having knitting devices including a series of needles movable as a unit, and individually movable yarn measuring sinkers, a sinker assembly which comprises means for serially projecting the sinkers, a catch bar, a verge plate, a grooved sinker support, and sinkers having top and bottom guide surfaces engaging in said grooves and butting surfaces for engagement with each of the sinker projecting means, the catch bar and the verge plate, said butting surfaces being located within the planes of said top and bottom guide surfaces to permit removal of the sinkers forwardly through said slotted guide support.

72. In a flat knitting machine having knitting devices including a series of needles movable as a unit, and individually movable yarn measuring sinkers, the combination of fluid pressure actuating means for serially projecting the sinkers, a verge plate against which the sinkers are projected, supporting means for the verge plate arranged to permit removal of the verge plate, a slotted sinker support, and sinkers mounted therein having top and bottom guide surfaces engaging in said slotted support, and having a verge plate engaging butt located between the planes comprised by said top and bottom guide surfaces to facilitate removal of the sinkers forwardly through said slotted support.

73. In a knitting machine having knitting devices including a needle series, a series of yarn measuring sinkers cooperating therewith, and means for feeding yarn to the sinkers, the combination of actuating means for the sinkers which comprises a series of round pins, one for each sinker, the diameter of which exceeds the index of the sinkers, said pins being positioned in staggered relation to one another, and means acting on said pins to advance the sinkers.

74. In a flat knitting machine having knitting devices including a series of needles movable as a unit, and individually movable yarn measuring sinkers, the combination of actuating means for the sinkers, fluid pressure actuated means for serially projecting the sinkers, which comprises an individual slider abutting each sinker to advance the sinker, and an individual fluid actuated element arranged to act on each of said sliders.

75. In a flat knitting machine having knitting devices including a series of needles movable as a unit, and individually movable yarn measuring sinkers one for each needle, the combination of

actuating means for the sinkers which comprises an individual slider abutting each sinker to advance the sinker, fluid pressure sinker projecting means acting serially on said sliders, means for controlling the rate of serial actuation and the rate of movement of each individually actuated sinker, a verge plate, a catch bar, butts formed on the sinkers for engagement with said verge plate and catch bar, and actuating means for moving said catch bar to permit the serial advance of all of said sinkers, and thereafter to move said catch bar to engage with and impart positioning movements to said sinkers en masse.

76. In a flat knitting machine having knitting devices including a series of needles movable as a unit, and individually movable yarn measuring sinkers, one for each needle, the combination of actuating means for the sinkers which comprises an individual slider abutting each sinker to advance the sinker, fluid pressure sinker projecting means acting serially on said sliders, means for controlling the rate of serial actuation and the rate of movement of each individually actuated sinker, a verge plate, and a catch bar located beneath the sinkers, butts formed on the under side of the sinkers for engagement with said verge plate and catch bar, and actuating means for said catch bar to permit the serial advance of all of said sinkers, and thereafter for moving said catch bar to engage with and impart positioning movements to said catch bar and sinkers en masse.

77. In a flat knitting machine having knitting devices including a needle series, a series of yarn measuring sinkers cooperating therewith, and means for feeding yarn to the sinkers, the combination of fluid pressure actuated means for advancing the sinkers, and sinker release cam means movable lengthwise of the sinker series to release the sinkers in accordance with a knitting wave.

78. In a flat knitting machine having knitting devices including a needle series, a series of yarn measuring sinkers cooperating therewith, and means for feeding yarn to the sinkers, the combination of fluid pressure actuated means for advancing the sinkers, sinker release cam means movable lengthwise of the sinker series to release the sinkers in accordance with a knitting wave, a catch bar for retracting the sinkers, and means operable to maintain said sinker release cam means out of sinker contact during said retracting movement of the sinkers.

MAX C. MILLER.
